18-O-HETERO-RESERPATES

Robert Armistead Lucas, Mendham, N.J., assignor to
Ciba Corporation, a corporation of Delaware
No Drawing. Filed Jan. 7, 1960, Ser. No. 931
15 Claims. (Cl. 260—287)

The present invention concerns compounds derived from deserpidic acids. More particularly, it relates to compounds of the formula:

in which R₁ represents lower alkyl, lower alkoxy-lower alkyl or tertiary amino-lower alkyl, R₂ stands for lower alkyl, R₃ represents cyclo-oxa-alkyl, particularly 2-cyclo-oxa-alkyl, which contains at least five atoms as ring members, each of the radicals R₄ and R₅ stands for hydrogen, lower aliphatic hydrocarbon, or a functional group, such as, for example, etherified hydroxyl, esterified hydroxyl, etherified mercapto, nitro, amino, halogeno or halogeno-lower alkyl, or, when attached to adjacent positions and taken together, for lower alkylene-dioxy, and R₆, attached to either one of the positions 5 or 6, stands for hydrogen or lower alkyl, salts or N-oxides thereof, as well as process for the preparation of such compounds.

A lower alkyl group R₁, containing from one to seven, preferably from one to four, carbon atoms, stands, for example, for methyl, ethyl, n-propyl, isopropyl, n-butyl, isobutyl as well as n-pentyl, isopentyl, n-hexyl and the like.

In a lower alkoxy-lower alkyl group R₁, the lower alkoxy portion contains from one to four carbon atoms and represents, for example, methoxy, ethoxy, n-propoxy, isopropoxy, n-butoxy and the like. The amino group of a tertiary amino-lower alkyl radical R₁ is primarily an N,N-di-lower alkyl-amino group, in which lower alkyl contains from one to four carbon atoms, e.g. N,N-dimethylamino, N-ethyl-N-methyl-amino, N,N-diethyl-amino, N,N-di-n-propylamino, N,N-di-isopropylamino and the like, an N,N-lower alkylene-imino group, in which lower alkylene contains from four to six carbon atoms, e.g. 1-pyrrolidino, 1-piperidino, 1-hexamethyleneimino and the like, an N,N-lower oxa-alkylene-imino group, in which lower oxa-alkylene contains preferably four carbon atoms, e.g. 1-morpholino and the like, or an N,N-lower aza-alkylene contains preferably four carbon atoms, e.g. 4-methyl-1-piperazine and the like.

The lower alkyl portion of a lower alkoxy-lower alkyl or a tertiary amino-lower alkyl radical R₁ is represented by a lower alkylene radical containing from two to seven carbon atoms, which separates the lower alkoxy group or the amino group from the carbon atom of the carboxy group by at least two carbon atoms. Preferably, the lower alkylene radical contains from two to three carbon atoms and separates the lower alkoxy and the amino group from the carboxy group by the same number of carbon atoms. Such radicals are primarily 1,2-ethylene, 1-methyl-1,2-ethylene, 2-methyl-1,2-ethylene or 1,3-propylene; other lower alkylene radicals may be, for example, 1,4-butylene or 1-methyl-1,3-propylene and the like.

The lower alkyl group R₂, containing from one to four carbon atoms, stands for ethyl, n-propyl, isopropyl, n-

2

butyl, isobutyl and the like, but represents above all methyl.

- The 2-cyclo-oxa-alkyl radical R₃, attached to the oxygen atom of the position 18 of the deserpidate portion is more especially represented by a 2-cyclo-oxa-alkyl radical containing from five to seven atoms as ring members, such as a tetrahydro-2-furanyl (2-cyclo-oxapentyl), a tetrahydro-2-pyranyl (2-cyclo-oxahexyl), a 2-cyclo-oxaheptyl radical and the like.
- 10 The carbon atoms of the cyclo-oxa-alkyl, particularly a 2-cyclo-oxa-alkyl, nucleus may be unsubstituted or substituted by lower aliphatic hydrocarbon, particularly lower alkyl, e.g. methyl, ethyl, n-propyl, isopropyl, n-butyl, isobutyl and the like, as well as, for example, lower cyclo-alkyl, e.g. cyclopentyl, cyclohexyl and the like, or carbocyclic aryl, such as monocyclic or bicyclic carbocyclic aryl, e.g. phenyl, naphthyl and the like, or carbocyclic aryl-lower aliphatic hydrocarbon, such as monocyclic or bicyclic carbocyclic aryl-lower alkyl, e.g. benzyl, 1-phenyl-ethyl, 2-phenylethyl and the like. Two of the carbon atoms of the cyclo-oxa-alkyl nucleus may also be part of a second, especially of a carbocyclic, ring system fused onto the cyclo-oxa-alkyl nucleus; carbocyclic rings, which may be fused onto the cyclo-oxa-alkyl nucleus, may be represented, for example, by cycloalkyl containing from five to seven carbon atoms, e.g. cyclopentyl, cyclohexyl, cycloheptyl and the like, or carbocyclic aryl, such as monocyclic or bicyclic carbocyclic aryl, e.g. phenyl, naphthyl and the like.
- 15 Other substituents attached to any of the available carbon atoms of the cyclo-oxa-alkyl, particularly the 2-cyclo-oxa-alkyl, radical are, for example, halogen atoms, e.g. fluorine, chlorine, bromine and the like, as well as other functional groups.
- 20 The group R₃ may, therefore, be represented by tetrahydrofuranyl (cyclo-oxapentyl) radicals, particularly tetrahydro-2-furanyl (2-cyclo-oxapentyl) radicals, e.g. tetrahydro-2-furanyl (2-cyclo-oxapentyl), 4-methyl-tetrahydro-2-furanyl (4-methyl-2-cyclo-oxapentyl), 5-methyl-tetrahydro-2-furanyl (5-methyl-2-cyclo-oxapentyl), 3-chloro-tetrahydro-2-furanyl (3-chloro-2-cyclo-oxapentyl) and the like, tetrahydropyranyl (cyclo-oxahexyl) radicals, particularly tetrahydro-2-pyranyl (2-cyclo-oxahexyl) radicals, e.g. tetrahydro-2-pyranyl (2-cyclo-oxahexyl), 4-methyl-tetrahydro-2-pyranyl (4-methyl-2-cyclo-oxahexyl), 6-methyl-tetrahydro-2-pyranyl (6-methyl-2-cyclo-oxahexyl), 6-phenyl-tetrahydro-2-pyranyl (6-phenyl-2-cyclo-oxahexyl), hexahydrobenz[e]tetrahydro-2-pyranyl (bicyclo[4,4,0]2-oxa-3-decyl), benz[e]dihydro-2-pyranyl (2-benz[e]cyclo-oxahexyl), 3-chloro-tetrahydro-2-pyranyl (3-chloro-2-cyclo-oxahexyl), 3-bromo-tetrahydro-2-pyranyl (3-bromo-2-cyclo-oxahexyl) and the like, or cyclo-oxaheptyl radicals, particularly 2-cyclo-oxaheptyl radicals, e.g. 2-cyclo-oxaheptyl and the like.
- 25 The substituents R₄ and R₅ may represent hydrogen or any of the groups mentioned hereinabove. Such groups are, for example, lower aliphatic hydrocarbon, primarily lower alkyl containing from one to four carbon atoms, e.g., methyl, ethyl, n-propyl, isopropyl and the like, or functional groups, such as, for example, etherified hydroxy, particularly lower alkoxy containing from one to four carbon atoms, e.g. methoxy, ethoxy, n-propoxy, isopropoxy, n-butoxy, i-butoxy, and the like, as well as cycloalkyloxy, e.g. cyclohexyloxy and the like, carbocyclic aryoxy, such as monocyclic carbocyclic aryl-lower alkoxy, e.g. phenoxy and the like, carbocyclic aryl-lower alkoxy, such as monocyclic carbocyclic aryl-lower alkoxy, for example, phenyl-lower alkoxy, e.g. benzyloxy and the like, esterified hydroxyl, particularly lower alkoxy-carbonyloxy, e.g. methoxycarbonyloxy, ethoxycarbonyloxy and the like, or lower alkanoyloxy, e.g. acetoxy, propionyloxy and the like, etherified mercapto, particularly low-

er alkyl-mercapto containing from one to four carbon atoms, e.g. methylmercapto, ethylmercapto and the like, nitro, amino, particularly N,N-disubstituted amino, such as N,N-di-lower alkyl-amino, e.g. N,N-dimethylamino, N,N-diethylamino and the like, halogeno, e.g. fluoro, chloro, bromo, iodo and the like, halogeno-lower alkyl, e.g. trifluoromethyl and the like, or any other suitable functional group. Whenever attached to two adjacent positions, the radicals R_4 and R_5 , when taken together, may also form a cyclic substituent; such substituent may be represented, for example, by lower alkylene-dioxy, e.g. methylenedioxy, or any other analogous substituent.

The radical R_6 stands preferably for hydrogen; when representing lower alkyl, such radical may stand for methyl, as well as ethyl and the like.

Salts of the compounds of this invention are primarily therapeutically acceptable acid addition salts with inorganic or organic acids, particularly with mineral acids, e.g. hydrochloric, hydrobromic, sulfuric, phosphoric acids and the like.

Due to the presence of a tertiary amino group in the molecule, the compounds may also be present in the form of their N-oxides.

In view of the fact that several asymmetric carbon atoms are present in the compounds of this invention, the latter may be obtained in the form of a mixture of racemates, racemates or optically pure compounds.

The new compounds of this invention have antihypertensive properties, as well as sedative and tranquilizing effects on the central nervous system. They are characterized by a quick onset of the physiological action. Furthermore, tests show that animals, treated with the compounds of the present invention, recover faster and more completely from the pharmacological effects than those treated with known, naturally occurring *Rauwolfia* alkaloids, for example, with reserpine, deserpidine or rescinnamine. In addition, certain quantitative differentiations may be observed within the group of the new compounds of this invention. For example, when compared with the established ratio existing between antihypertensive and sedative effects in the above-mentioned natural *Rauwolfia* alkaloids, some of the compounds of this invention have more predominant sedative effects with negligible antihypertensive activity, whereas in others, the latter may be more pronounced than the sedative and tranquilizing component.

The compounds of the present invention may, therefore, be used as antihypertensive agents to relieve hypertensive conditions, such as, for example, benign or malignant hypertension, renal hypertension or hypertension associated with pregnancy, such as toxemia of pregnancy, and/or as sedative agents to relieve states of hyperactivity, tension and agitation, as, for example, associated with mental disturbances and the like.

Very pronounced antihypertensive and/or sedative effects are exhibited by compounds of the formula:

in which R_1 represents lower alkyl containing from one to four carbon atoms, lower alkoxy-lower alkyl, in which lower alkoxy contains from one to four carbon atoms and lower alkyl, containing from two to three carbon atoms, separates lower alkoxy from the carboxy group by from two to three carbon atoms, or N,N -di-lower alkyl-amino-lower alkyl, in which lower alkyl of the N,N -di-lower alkyl-amino portion contains from one to four

carbon atoms, and lower alkyl, separating N,N-di-lower alkyl-amino from the carboxy group by two to three carbon atoms, contains from two to three carbon atoms, R_2 represents lower alkyl containing from one to four carbon atoms, R_3 stands for 2-cyclo-oxa-alkyl containing from five to seven atoms as ring members, lower alkyl-substituted 2-cyclo-oxa-alkyl containing from five to seven atoms as ring members, or halogeno-substituted 2-cyclo-oxa-alkyl containing from five to seven atoms as ring members, each of the radicals R_4 and R_5 stands for hydrogen, lower alkyl containing from one to four carbon atoms, lower alkoxy containing from one to four carbon atoms, lower alkyl-mercapto containing from one to four carbon atoms, or halogeno, R_6 , attached to one of the positions 5 and 6, stands for hydrogen or lower alkyl containing from one to four carbon atoms, the therapeutically useful mineral acid addition salts or the N-oxides of these compounds, as well as their various isomeric forms.

20 This group of compounds is represented, for example, by lower alkyl reserpate compounds of the formula:

in which R_1 stands for lower alkyl containing from one to four carbon atoms, or the N -oxides thereof, whereby these compounds may be in different isomeric forms.

35 Specific members illustrating this group of compounds are lower alkyl 18-O-(tetrahydro-2-furanyl)-reserpates, in which lower alkyl contains from one to four carbon atoms, e.g. methyl 18-O-(tetrahydro-2-furanyl)-reserpate, ethyl 18-O-(tetrahydro-2-furanyl)-reserpate, n-propyl 18-O-(tetrahydro-2-furanyl)-reserpate, n-butyl 18-O-(tetrahydro-2-furanyl)-reserpate.

40 rahydro-2-furanyl)-reserpate and the like, lower alkyl 18-O-(tetrahydro-2-pyranyl)-reserpates, in which lower alkyl contains from one to four carbon atoms, e.g. methyl 18-O-(tetrahydro-2-pyranyl)-reserpate, ethyl 18-O-(tetrahydro-2-pyranyl)-reserpate, n-propyl 18-O-(tetrahydro-2-pyranyl)-reserpate, isopropyl 18-O-(tetrahydro-2-pyranyl)-reserpate.

45 2-pyranyl)-reserpate, isopropyl 18-O-(tetrahydro-2-pyranyl)-reserpate, n-butyl 18-O-(tetrahydro-2-pyranyl)-reserpate, isobutyl 18-O-(tetrahydro-2-pyranyl)-reserpate, n-pentyl 18-O-(tetrahydro-2-pyranyl)-reserpate and the like, or the lower alkyl 18-O-(2-cyclo-oxaheptyl)-reserpates in which lower alkyl contains from one to four carbon

50 ates, in which lower alkyl contains from one to four carbon atoms, e.g. methyl 18-O-(2-cyclo-oxaheptyl)-reserpate, ethyl 18-O-(2-cyclo-oxaheptyl)-reserpate, n-propyl 18-O-(2-cyclo-oxaheptyl)-reserpate and the like, and the N-oxides of such compounds, which compounds may be
 55 present in different isomeric forms.

The above group of compounds may also be represented by those of the formula:

in which R₁ stands for lower alkyl containing from one to four carbon atoms, or their N-oxides, whereby these compounds may be in different isomeric forms. Lower alkyl 18-O-(tetrahydro-2-furanyl)-deserpipidates, in which lower alkyl contains from one to four carbon atoms, e.g., methyl 18-O-(tetrahydro-2-furanyl)-deserpipidate, ethyl 18-O-(tetrahydro-2-furanyl)-deserpipidate and the like, lower alkyl 18-O-(2-cyclo-oxaheptyl)-deserpipidates, in which

lower alkyl contains from one to four carbon atoms, e.g. methyl 18-O-(tetrahydro-2-pyranyl)-deserpdate, ethyl 18-O-(tetrahydro-2-pyranyl)-deserpdate, n-propyl 18-O-(tetrahydro-2-pyranyl)-deserpdate and the like, or lower alkyl 18-O-(2-cyclo-oxaheptyl)-deserpdates, in which lower alkyl contains from one to four carbon atoms, e.g. methyl 18-O-(2-cyclo-2-oxaheptyl)-deserpdate, ethyl 18-O-(2-cyclo-oxaheptyl)-deserpdate and the like, and the N-oxides of such compounds, which compounds may be present in different isomeric forms, represent this group.

The new compounds may also be represented by the 2-lower alkoxy-lower alkyl 18-O-R₃-11-R₄-deserpdates, in which lower alkoxy contains from one to four carbon atoms, lower alkyl contains from two to three carbon atoms and separates alkoxy from the carboxy group by from two to three carbon atoms, R₃ represents 2-cyclo-oxa-alkyl containing from five to seven atoms as ring members, and R₄ represents hydrogen or methoxy. This group is represented by 2-lower alkoxy-ethyl 18-O-(tetrahydro-2-furanyl)-reserpates, in which alkoxy contains from one to four carbon atoms, such as 2-methoxy-ethyl 18-O-(tetrahydro-2-furanyl)-reserpate and the like, and the 2-lower alkoxy-ethyl 18-O-(tetrahydro-2-furanyl)-deserpdates, in which lower alkoxy contains from one to four carbon atoms, such as 2-methoxyethyl 18-O-(tetrahydro-2-furanyl)-deserpdate and the like, 2-lower alkoxy-ethyl 18-O-(tetrahydro-2-furanyl)-reserpates, in which alkoxy contains from one to four carbon atoms, such as 2-methoxy-ethyl 18-O-(tetrahydro-2-furanyl)-reserpate and the like, and the 2-lower alkoxy-ethyl 18-O-(tetrahydro-2-furanyl)-deserpdates, in which lower alkoxy contains from one to four carbon atoms, such as 2-methoxyethyl 18-O-(tetrahydro-2-furanyl)-deserpdate and the like.

An additional group of the new compounds is represented by the lower alkyl 10-methoxy-18-O-R₃-deserpdates, in which R₃ stands for 2-cyclo-oxa-alkyl containing from five to seven atoms as ring members, and lower alkyl contains from one to four carbon atoms; such compounds are, for example, lower alkyl 10-methoxy-18-O-(tetrahydro-2-furanyl)-deserpdate, in which lower alkyl contains from one to four carbon atoms, e.g. methyl 10-methoxy-18-O-(tetrahydro-2-furanyl)-deserpdate, ethyl 10-methoxy-18-O-(tetrahydro-2-furanyl)-deserpdate, n-propyl 10-methoxy-18-O-(tetrahydro-2-furanyl)-deserpdate and the like, lower alkyl 10-methoxy-18-O-(tetrahydro-2-furanyl)-deserpdate, in which lower alkyl contains from one to four carbon atoms, e.g. methyl 10-methoxy-18-O-(tetrahydro-2-furanyl)-deserpdate, ethyl 10-methoxy-18-O-(tetrahydro-2-furanyl)-deserpdate, n-propyl 10-methoxy-18-O-(tetrahydro-2-furanyl)-deserpdate and the like.

A further group of highly active compounds are the lower alkyl 12-methoxy-18-O-R₃-deserpdates, in which R₃ represents 2-cyclo-oxa-alkyl containing from five to seven atoms as ring members, and lower alkyl contains from one to four carbon atoms as ring members. This group may be illustrated by lower alkyl 12-methoxy-18-O-(tetrahydro-2-furanyl)-deserpdates, in which lower alkyl contains from one to four carbon atoms; methyl 12-methoxy-18-O-(tetrahydro-2-furanyl)-deserpdate, ethyl 12-methoxy-18-O-(tetrahydro-2-furanyl)-deserpdate, n-propyl 12-methoxy-18-O-(tetrahydro-2-furanyl)-deserpdate and the like, lower alkyl 12-methoxy-18-O-(tetrahydro-2-furanyl)-deserpdates, in which lower alkyl contains from one to four carbon atoms; methyl 12-methoxy-18-O-(tetrahydro-2-furanyl)-deserpdate, ethyl 12-methoxy-18-O-(tetrahydro-2-furanyl)-deserpdate, n-propyl 12-methoxy-18-O-(tetrahydro-2-furanyl)-deserpdate and the like, are specific examples of such compounds.

Lower alkyl 10-halogeno-18-O-R₃-deserpdates, in which R₃ stands for 2-cyclo-oxa-alkyl containing from five to seven atoms as ring members, halogeno represents primarily chloro or bromo, as well as iodo, and lower alkyl contains from one to four carbon atoms, are an additional series of new compounds of this invention.

Lower alkyl 10-chloro-18-O-(tetrahydro-2-furanyl)-reserpates, lower alkyl 10-bromo-18-O-(tetrahydro-2-furanyl)-reserpates, lower alkyl 10-chloro-18-O-(tetrahydro-2-pyranyl)-deserpdates and lower alkyl 10-bromo-18-O-(tetrahydro-2-pyranyl)-deserpdates, in which lower alkyl contains from one to four carbon atoms, illustrate this group; methyl 10-chloro-18-O-(tetrahydro-2-furanyl)-deserpdate, ethyl 10-chloro-18-O-(tetrahydro-2-furanyl)-deserpdate, n-propyl 10-chloro-18-O-(tetrahydro-2-furanyl)-deserpdate, methyl 10-bromo-18-O-(tetrahydro-2-furanyl)-deserpdate, ethyl 10-bromo-18-O-(tetrahydro-2-furanyl)-deserpdate, n-propyl 10-bromo-18-O-(tetrahydro-2-furanyl)-deserpdate and the like, methyl 10-chloro-18-O-(tetrahydro-2-pyranyl)-deserpdate, ethyl 10-chloro-18-O-(tetrahydro-2-pyranyl)-deserpdate, n-propyl 10-chloro-18-O-(tetrahydro-2-pyranyl)-deserpdate, methyl 10-bromo-18-O-(tetrahydro-2-pyranyl)-deserpdate, ethyl 10-bromo-18-O-(tetrahydro-2-pyranyl)-deserpdate, n-propyl 10-bromo-18-O-(tetrahydro-2-pyranyl)-deserpdate and the like, are specific members of such compounds.

An additional group of compounds are the lower alkyl 6-methyl-18-O-R₃-reserpates, in which R₃ stands for 2-cyclo-oxa-alkyl containing from five to seven atoms as ring members, and lower alkyl contains from one to four carbon atoms. The lower alkyl 6-methyl-18-O-(tetrahydro-2-furanyl)-reserpates and the lower alkyl 6-methyl-18-O-(tetrahydro-2-pyranyl)-reserpates, in which lower alkyl contains from one to four carbon atoms, are more specific groups of these compounds, which may be illustrated, for example, by methyl 6-methyl-18-O-(tetrahydro-2-furanyl)-reserpate, ethyl 6-methyl-18-O-(tetrahydro-2-furanyl)-reserpate, n-propyl 6-methyl-18-O-(tetrahydro-2-furanyl)-reserpate and the like, methyl 6-methyl-18-O-(tetrahydro-2-pyranyl)-reserpate, ethyl 6-methyl-18-O-(tetrahydro-2-pyranyl)-reserpate, n-propyl 6-methyl-18-O-(tetrahydro-2-pyranyl)-reserpate and the like.

Other lower alkyl 18-O-R₃-deserpdate compounds, in which R₃ represents 2-cyclo-oxa-alkyl containing from five to seven atoms as ring members, and lower alkyl contains from one to four carbon atoms, are, for example, lower alkyl 5-methyl-18-O-R₃-deserpdates, lower alkyl 5-methyl-18-O-R₃-reserpates, lower alkyl 6-methyl-18-O-R₃-deserpdates, lower alkyl 9-methyl-18-O-R₃-deserpdates, lower alkyl 11-methyl-18-O-R₃-deserpdates, lower alkyl 9-methoxy-18-O-R₃-deserpdates, lower alkyl 10-methoxy-18-O-R₃-reserpates, lower alkyl 11-ethoxy-18-O-R₃-deserpdates, lower alkyl 11-n-propyloxy-18-O-R₃-deserpdates, lower alkyl 11-isopropoxy-18-O-R₃-deserpdates, lower alkyl 11-n-butyloxy-18-O-R₃-deserpdates, lower alkyl 10, 11-methylenedioxy-18-O-R₃-deserpdates, lower alkyl 10-benzylxy-18-O-R₃-deserpdates, lower alkyl 11-benzylxy-18-O-R₃-deserpdates, lower alkyl 11-methylmercapto-18-O-R₃-deserpdates, lower alkyl 11-ethylmercapto-18-O-R₃-deserpdates, lower alkyl 17-desmethoxy-17-ethoxy-18-O-R₃-deserpdates, lower alkyl 17-desmethoxy-17-n-propyloxy-18-O-R₃-reserpates, lower alkyl 17-desmethoxy-17-isopropoxy-18-O-R₃-reserpates and the like, in which R₃ represents cyclo-oxa-alkyl containing from five to seven atoms as ring members, represented primarily by tetrahydro-2-furanyl or tetrahydro-2-pyranyl, and in which lower alkyl contains from one to four carbon atoms.

The compounds of this invention may be used as medicaments in the form of pharmaceutical preparations, which contain the new compounds in admixture with a pharmaceutical organic or inorganic, solid or liquid carrier suitable for enteral or parenteral administration. For making up the preparations there can be employed substances which do not react with the new compounds, such as water, gelatine, lactose, starches, magnesium stearate, stearyl alcohol, talc, vegetable oils, benzyl alcohols, gums, waxes, propylene glycol, polyalkylene glycols or any other known carrier for medicaments. The pharmaceutical preparations may be in solid form, for example, as tablets, dragees, capsules and the like, or in liquid form, for example, as solutions, suspensions, emulsions and

the like. If desired, they may contain auxiliary substances such as preserving, stabilizing, wetting or emulsifying agents and the like, salts for varying the osmotic pressure, buffers and the like. They may also contain, in combination, other therapeutically useful substances. The compounds of this invention may also be used in compositions for veterinary use by adding them to standard feed formulae.

Compounds of the present invention may be prepared by reacting a deserpide compound of the formula:

in which R₁, R₂, R₄, R₅ and R₆ have the previously given meaning, or an N-oxide thereof, with a reactive ester of a 2-hydroxy-cyclo-oxa-alkane, which contains at least five atoms as ring members, in the presence of a condensing reagent, and, if desired, separating a resulting mixture of isomeric compounds into the single isomers, and/or, if desired, converting a resulting compound into a salt or an N-oxide thereof.

The reactive ester of a 2-hydroxy-cyclo-oxa-alkane, used as the reagent in the above reaction, is particularly an ester with a strong inorganic or organic acid, particularly a mineral acid, such as a hydrohalic acid, e.g. hydrochloric, hydrobromic acid and the like, as well as a monocyclic carbocyclic aryl sulfonic acid, e.g. p-tolene sulfonic acid and the like. The reagent is represented primarily by a 2-halogeno-cyclo-oxa-alkane, which contains at least five atoms as ring members, particularly by a 2-chloro-cyclo-oxa-alkane, as well as by a 2-bromo-cyclo-oxa-alkane, which contain from five to seven atoms as ring members. Specific reagents are, for example, 2-chloro-tetrahydrofuran (2-chloro-cyclo-oxapentane), 2-chloro-tetrahydropyran (2-chloro-cyclo-oxahexane), 2-chloro-cyclo-oxahexane, as well as the corresponding bromo derivatives. The above cyclo-oxa-alkane compounds may contain hydrocarbon radicals, such as, for example, lower alkyl, e.g. methyl and the like, or functional groups, such as additional halogen atoms, e.g. chlorine and the like, or any other suitable substituent; substituted reagents are, for example, 2-chloro-5-methyl-tetrahydrofuran (2-chloro-5-methyl-cyclo-oxapentane), 2-chloro-4-methyl-tetrahydropyran (2-chloro-4-methyl-cyclo-oxahexane), 2-chloro-6-methyl-tetrahydropyran (2-chloro-6-methyl-cyclo-oxahexane), 2,3-dichloro-tetrahydropyran (2,3-dichloro-cyclo-oxahexane) and the like.

A condensing reagent may be represented more particularly by N,N-dimethylformamide; any other suitable reagent may be used. N,N-dimethylformamide may also serve as a solvent; other inert solvents may be used as diluents.

Ordinarily, the reaction mixture is allowed to stand, if necessary, while cooling and with protection from light, until the reaction is completed. The desired compound is isolated from the reaction mixture according to methods known per se, for example, by evaporating the solvent and isolating the reaction product from the residue, by diluting the reaction mixture and precipitating or extracting the product, and the like. The reaction product may be purified by crystallization, adsorption and elution, recrystallization and the like.

The deserpide compounds used as the starting materials are known or, if new, may be prepared according to procedures used for known analogous compounds. For example, deserpidic acids may be esterified by treatment with a lower diazoalkane, a lower alkoxy-lower diazoalkane or a tertiary amino-lower diazoalkane, or

by alcoholysis of deserpidic acid (16-18)-lactones with alkali metal compounds of lower alkanols, lower alkoxy-lower alkanols or tertiary amino-lower alkanols.

For example, to a solution of the diazo reagent in an inert solvent, such as an ether, particularly diethylether, may be added the deserpidic acid compound or a salt thereof, which is preferably kept in a suspension or a solution, for example, of a lower alkanol, e.g. methanol, ethanol and the like, a halogenated lower aliphatic hydrocarbon, e.g. chloroform, methylene chloride and the like, or any other suitable, inert solvent. Or, the diazo compound may be distilled out of a solution, such as a diethylether solution, into the suspension or solution of a deserpidic acid compound or a salt thereof. An excess of the diazo derivative present in the reaction mixture may be destroyed, for example, by adding an additional carboxylic acid, e.g. acetic, benzoic acid and the like. The esterification may be carried out under cooling or at room temperature, and, if desired, under the atmosphere of an inert gas, e.g. nitrogen.

Or, by treating the necessary amount of an alkali metal, e.g. lithium, potassium, or particularly sodium, with a lower alkanol, a lower alkoxy-lower alkanol or a tertiary amino-lower alkanol and adding a deserpidic acid lactone to the resulting alkali metal derivative of the alcohol, the desired deserpide compound may be obtained. Although this reaction may proceed under cooling or at room temperature, the mixture is advantageously heated, if necessary, in the atmosphere of an inert gas, e.g. nitrogen.

N-oxides of the starting material may be prepared according to known N-oxidation methods; for example, a solution of the starting material may be treated with a per-acid, such as, for example, peracetic, perbenzoic, monoperphthalic, p-toluene persulfonic acid and the like, with hydrogen peroxide or with ozone.

Compounds of the present invention may also be prepared by reacting a deserpide of the formula:

in which R₁, R₂, R₄, R₅ and R₆ have the above-given meaning, a salt or an N-oxide thereof, with a cyclo-oxa-alk-2-ene, which contains at least five atoms as ring members, and which is capable of introducing the desired radical R₃, in the presence of an acid condensing reagent, and, if desired, converting a resulting salt into the free base, and/or, if desired, separating a resulting mixture of isomeric compounds into the single isomers, and/or, if desired, converting a resulting compound into a salt or an N-oxide thereof.

The cyclo-oxa-alk-2-enes used as the reagents, contain no further substituents, or, whenever substituents, such as halogen, lower alkyl and the like, are present, such substituents are attached to those carbon atoms, which do not involve the 2,3-double bond. Especially suitable reagents are cyclo-oxa-alk-2-enes, which contain from five to six atoms as ring members, and which, when substituted, contain such substituents attached to carbon atoms not involving the 2,3-double bond, such as, for example, 2,3-dihydrofuran (cyclo-oxapent-2-ene), e.g. 2,3-dihydrofuran (cyclo-oxapent-2-ene), 2-methyl-2,3-dihydrofuran (5-methyl-cyclo-oxapent-2-ene), and the like, 2,3-dihydropyrans (cyclo-oxahex-2-enes), e.g. 2,3-dihydropyran (cyclo-oxahex-2-ene), 4-methyl-2,3-dihydropyran (4-methyl-cyclo-oxahex-2-ene), 2-methyl-2,3-dihydropyran (6-methyl-cyclo-oxahex-2-ene), 2-chloro-2,3-dihydropyran (6-chloro-cyclo-oxahex-2-ene) and the like.

These reagents are reacted with the deserpide compound in the presence of an acid condensing reagent, represented by a strong Lewis acid. Mineral acids, e.g. hydrochloric, hydrobromic or sulfuric acid (used in anhydrous form or as concentrated aqueous solutions), phosphoric acid (for example, in the form of polyphosphoric acid), phosphorous oxychloride, fluoroboric acid (in the form of a highly concentrated aqueous solution), boron trifluoride (in the form of its etherate, particularly with diethyl ether), or a carbocyclic aryl sulfonic acid, such as a monocyclic carbocyclic acid, especially p-toluene sulfonic acid, or similar reagents having Lewis acid properties, such as, for example, cation exchange resins in acid form, e.g. sulfonic acid resins, or any other suitable Lewis acid may serve as a condensing reagent.

In the presence of the strong Lewis acid the deserpide compound may first form a salt with such acid and react in the form of an acid addition salt. Therefore, a salt of the deserpide compound with an acid may also be used as the starting material.

The reaction may be carried out in the absence of a solvent, whereby an excess of a liquid cyclo-oxa-alk-2-ene may also serve as the solvent, or in the presence of an inert solvent. Such solvents are, for example, carbocyclic aryl hydrocarbons, such as monocyclic carbocyclic aryl hydrocarbons, e.g. benzene, toluene and the like, ethers, e.g. diethylether, tetrahydrofuran, p-dioxane and the like, lower alkanes, e.g. acetone, ethyl methyl ketone and the like, formamides, e.g. formamide, N,N-dimethylformamide and the like, acetonitrile or any other suitable solvent.

The reaction may be carried out by mixing the reagents or solutions thereof, whereupon the temperature may raise, and the mixture may then be allowed to stand or may be agitated under cooling, at room temperature or at an elevated temperature. The desired product may be isolated according to standard procedures, e.g. extraction, adsorption and elution, crystallization, and the like, preferably after having neutralized the acidic reaction mixture with an alkaline reagent, for example, ammonia, e.g. aqueous ammonia, ammonia in a lower alkanol such as methanol, ethanol and the like, aqueous alkali metal carbonate, e.g. sodium or potassium carbonate or hydrogen carbonate and the like, aqueous alkali metal hydroxide, e.g. sodium hydroxide, potassium hydroxide and the like, or any other suitable alkaline reagent.

The reaction may also be carried out in the atmosphere of an inert gas, e.g. nitrogen and/or, if necessary, with the exclusion of moisture by adding a dehydrating reagent, or under pressure in a closed vessel.

The compounds of the present invention may also be prepared by converting in compounds of the formula:

in which R₂, R₃, R₄, R₅ and R₆ have the previously given meaning, a salt or an N-oxide thereof, the free carboxyl group in 16-position into an esterified carboxyl group of the formula R₁—O—(O=)C—, in which R₁ has the previously given meaning, and, if desired, carrying out the optional steps.

The esterification of the free carboxyl group may be carried out according to methods known per se, which are used for the preparation of analogous compounds. For example, the 18-O-R₃-deserpodic acid compounds, in which R₃ has the previously given meaning, may be treated with a diazo compound of the formula R₁N₂, in which R₁ has

the previously given meaning, particularly a lower diazoalkane, e.g. diazomethane, diazoethane, 1-diazopropane, 1-diazo-n-butane, 1-diazo-isobutane, 1-diazo-n-pentane, 1-diazo-isopentane, 1-diazo-n-hexane and the like, a lower 5 alkoxy-lower diazoalkane, particularly a lower alkoxy-lower diazoalkane, in which lower alkoxy is separated from the diazo group by from two to three carbon atoms, and lower alkane contains from two to three carbon atoms, e.g. 2-methoxy-diazoethane, 2-ethoxy-diazoethane, 2-n-10 propyloxy-diazoethane, 3-methoxy-1-diazopropane, 3-ethoxy-1-diazopropane and the like, or a tertiary amino-lower diazoalkane, particularly an N,N-di-lower alkyl-amino-lower diazoalkane, in which the N,N-di-lower alkyl-amino group is separated from the diazo group by from two to 15 three carbon atoms, and lower alkane contains from two to three carbon atoms, e.g. 2-N,N-dimethylamino-diazoethane, 2-N,N-diethylamino-diazoethane, 3-N,N-dimethylamino-1-diazopropane and the like. The reaction of the 18-O-R₃-deserpodic acid compounds with such diazo-reagents is carried out, for example, in the presence of a diluent, such as in a lower alkanol, e.g. methanol, ethanol, n-propanol, isopropanol and the like, a halogenated lower alkane, e.g. chloroform, methylene chloride and the like, or any other suitable solvent; preferably, the diazo-reagent 20 is used in solution, for example, in an ether solution. Cooling of the reaction mixture and/or the presence of an atmosphere consisting of an inert gas, e.g. nitrogen, may be required.

The starting materials used in the above process for the 25 preparation of the compounds of this invention are new and are intended to be included within the scope of the invention. They may be depicted by the formula:

45 in which the radicals R₂, R₃, R₄, R₅ and R₆ have the previously given meaning, salts and N-oxides of such compounds. Particularly useful are the compounds of the formula:

50 in which R₂ represents lower alkyl containing from one to four carbon atoms, R₃ stands for 2-cyclo-oxa-alkyl containing from five to seven atoms as ring members, lower alkyl-substituted 2-cyclo-oxa-alkyl containing from five to seven atoms as ring members, or halogeno-substituted 2-cyclo-oxa-alkyl containing from five to seven atoms as ring members, each of the groups R₄ and R₅ stands for hydrogen, lower alkyl containing from one to four carbon atoms, lower alkoxy containing from one to four carbon atoms,

55 lower alkyl-mercapto containing from one to four carbon atoms or halogeno, and R₆, attached to one of the positions 5 and 6, stands for hydrogen or lower alkyl containing from one to four carbon atoms, salts or the N-oxides of these compounds, as well as their various isomeric forms.

This group of compounds may be represented by reserpic acid compounds of the formula:

salt or N-oxides thereof. Specific compounds of this type are, for example, 18-O-(tetrahydro-2-furanyl)-reserpic acid, 18-O-(tetrahydro-2-pyranyl)-reserpic acid and the like. Another group of these compounds may be represented by the formula:

salt or N-oxides thereof. Specific compounds of this type are, for example, 18-O-(tetrahydro-2-furanyl)-deserpodic acid, 18-O-(tetrahydro-2-pyranyl)-deserpodic acid and the like.

Apart from the above-mentioned reserpic acids and deserpodic acids, other deserpodic acid-type compounds of the previously given formula, are, for example,

5-methyl-18-O-(tetrahydro-2-furanyl)-deserpodic acid, 5-methyl-18-O-(tetrahydro-2-furanyl)-reserpic acid, 6-methyl-18-O-(tetrahydro-2-furanyl)-deserpodic acid, 6-methyl-18-O-(tetrahydro-2-furanyl)-reserpic acid, 9-methyl-18-O-(tetrahydro-2-furanyl)-deserpodic acid, 10-methoxy-18-O-(tetrahydro-2-furanyl)-deserpodic acid, 10-methoxy-18-O-(tetrahydro-2-furanyl)-reserpic acid, 11-ethoxy-18-O-(tetrahydro-2-furanyl)-deserpodic acid, 12-methoxy-18-O-(tetrahydro-2-furanyl)-deserpodic acid, 10-chloro-18-O-(tetrahydro-2-furanyl)-deserpodic acid, 10-bromo-18-O-(tetrahydro-2-furanyl)-deserpodic acid, 10-bromo-18-O-(tetrahydro-2-furanyl)-reserpic acid, 17-desmethoxy-17-ethoxy-18-O-(tetrahydro-2-furanyl)-reserpic acid, 5-methyl-18-O-(tetrahydro-2-pyranyl)-deserpodic acid, 5-methyl-18-O-(tetrahydro-2-pyranyl)-reserpic acid, 6-methyl-18-O-(tetrahydro-2-pyranyl)-reserpic acid, 6-methyl-18-O-(tetrahydro-2-pyranyl)-deserpodic acid, 9-methyl-18-O-(tetrahydro-2-pyranyl)-deserpodic acid, 11-methyl-18-O-(tetrahydro-2-pyranyl)-deserpodic acid, 9-methoxy-18-O-(tetrahydro-2-pyranyl)-deserpodic acid, 10-methoxy-18-O-(tetrahydro-2-pyranyl)-deserpodic acid, 10-methoxy-18-O-(tetrahydro-2-pyranyl)-reserpic acid, 11-ethoxy-18-O-(tetrahydro-2-pyranyl)-deserpodic acid, 11-n-propyloxy-18-O-(tetrahydro-2-pyranyl)-deserpodic acid, 12-methoxy-18-O-(tetrahydro-2-pyranyl)-deserpodic acid, 11-methyl-mercapto-18-O-(tetrahydro-2-pyranyl)-deserpodic acid, 11-ethyl-mercapto-18-O-(tetrahydro-2-pyranyl)-deserpodic acid, 10,11-methylenedioxy-18-O-(tetrahydro-2-pyranyl)-deserpodic acid, 10-chloro-18-O-(tetrahydro-2-pyranyl)-deserpodic acid, 10-bromo-18-O-(tetrahydro-2-pyranyl)-deserpodic acid, 10-bromo-18-O-(tetrahydro-2-pyranyl)-reserpic acid, 17-desmethoxy-17-ethoxy-18-O-(tetrahydro-2-pyranyl)-reserpic acid

and the like, as well as salts or N-oxides thereof. As shown hereinabove, these deserpodic acid compounds or salts thereof may be converted into the desired deserpide

compounds by treatment, for example, with lower diazoalkanes, lower alkoxy-lower diazoalkanes, in which lower alkoxy is separated from the diazo group by from two to three carbon atoms, and lower alkane contains from two to three carbon atoms, N,N-di-lower alkyl-amino-lower diazoalkanes, in which the N,N-di-lower alkyl-amino group is separated from the diazo group by from two to three carbon atoms, and lower alkane contains from two to three carbon atoms.

The deserpodic acid compounds used as the intermediates may be prepared, for example, by treating a deserpodic acid compound of the formula:

in which R₂, R₄, R₅ and R₆ have the previously given meaning, or an N-oxide thereof, with a reactive ester of a 2-hydroxy-cyclo-oxa-alkane, which contains at least five atoms as ring members, in the presence of a condensation reagent, and, if desired, separating a resulting mixture of isomeric compounds into the single isomers, and/or, if desired, converting a resulting salt into a free compound, and/or, if desired, converting a resulting compound into a salt or an N-oxide thereof.

This reaction may be carried out as shown hereinabove. 2-halogeno-cyclo-oxa-alkanes, primarily 2-chloro-cyclo-oxa-alkanes, which contain from five to seven atoms as ring members, e.g. 2-chloro-tetrahydrofuran (2-chloro-cyclo-oxapentane), 2-chloro-tetrahydropyran (2-chloro-cyclo-oxahexane) and the like are used as the preferred reagents, and N,N-dimethylformamide is a very suitable condensing reagent, which may simultaneously serve as a solvent.

The starting materials may also be prepared by treating a deserpodic acid compound of the formula:

in which R₂, R₄, R₅ and R₇ have the above-given meaning, a salt or an N-oxide thereof, with a cyclo-oxa-alk-2-ene containing at least five atoms as ring members, in the presence of an acid condensing reagent, and, if desired, carrying out the optional steps.

The above reaction is carried out according to the previously shown procedure; a cyclo-oxa-alk-2-ene containing from five to six atoms as ring members, such as the previously described 2,3-dihydrofuran (cyclo-oxapent-2-enes), 2,3-dihydropyran (cyclo-oxa-hex-2-enes) and the like, are used as the preferred reagents, and an acid condensing reagent, such as a mineral acid, p-toluenesulfonic acid and the like, is used to promote the reaction.

The deserpodic acids used as starting materials may also be prepared, for example, by replacing in deserpide

compounds or N-oxides thereof, these compounds having the formula:

in which R_2 , R_3 , R_4 , R_5 and R_6 have the previously given meaning, and R_1' represents lower alkyl, lower alkoxy-lower alkyl, tertiary amino-lower alkyl or the group of the formula $Ph-(Z)CH-$, in which Ph represents monocyclic carbocyclic aryl and Z stands for hydrogen or lower alkyl, the esterified carboxyl group in 16-position by a free carboxyl group, and, if desired, carrying out the optional steps.

Lower alkyl, lower alkoxy-lower alkyl and tertiary amino-lower alkyl, representing R_1' , are identical with the radicals standing for the previously defined R_1 . The monocyclic carbocyclic aryl radical Ph in the formula $Ph-(Z)CH-$ stands primarily for phenyl; it may also be represented by substituted phenyl, whereby substituents may be lower alkyl, e.g. methyl and the like, lower alkoxy, e.g. methoxy and the like, or halogen, e.g. chlorine, bromine and the like, or any other substituents, which do not hinder the departure of the monocyclic carbocyclic arylmethyl radical. Although Z may represent lower alkyl, e.g. methyl, ethyl, n-propyl and the like, it stands primarily for hydrogen.

The radical R_1' in the above-depicted formula for the intermediate may be replaced by hydrogen by way of hydrolytic cleavage. This reaction may be carried out according to known methods, for example, by treatment with an alkaline reagent, such as, for example, with a solution of an alkali metal hydroxide, e.g. lithium hydroxide, sodium hydroxide, potassium hydroxide and the like, in an appropriate solvent such as a lower alkanol, e.g. methanol, ethanol and the like, water, an aqueous lower alkanol and the like.

The group $Ph-(Z)CH-$, in which the Ph and Z have the previously given meaning, may also be removed by hydrogenolysis, i.e. by reacting the intermediate, preferably a solution thereof, for example, in a lower alkanol, e.g. methanol, ethanol and the like, with hydrogen in the presence of a catalyst. Such catalyst contains a metal of the eighth group of the periodic system, for example, palladium and the like, and may be represented by palladium black or any other suitable catalyst. If necessary, increased pressure and/or elevated temperature may be employed, although normally the reaction proceeds under atmospheric pressure and at room temperature. In order to secure a complete hydrogenolysis, the reaction vessel is agitated to expose the catalyst to the hydrogen.

The intermediates, which are used in the above reaction and in which R_1' represents lower alkyl, lower alkoxy-lower alkyl or tertiary amino-lower alkyl, are identical with the previously described products, in which R_1' is replaced by the radical R_1 ; those compounds may be used as intermediates in the preparation of final products, in which R_1' and R_1 have different meanings.

Other intermediates useful in the above preparation of starting materials are the compounds of the formula:

in which R_2 , R_3 , R_4 , R_5 , R_6 , Ph and Z have the previously given meaning, and salts thereof; they are new and are intended to be included within the scope of this invention.

Particularly useful as intermediates in the above reaction

are the compounds of the formula:

in which R_2 represents lower alkyl containing from one to four carbon atoms, R_3 stands for 2-cyclo-oxa-alkyl containing from five to seven atoms as ring members, lower alkyl-substituted 2-cyclo-oxa-alkyl containing from five to seven atoms as ring members, or halogeno-substituted 2-cyclo-oxa-alkyl containing from five to seven atoms as ring members, each of the groups R_4 and R_5 stands for hydrogen, lower alkyl containing from one to four carbon atoms, lower alkoxy containing from one to four carbon atoms, lower alkyl-mercapto containing from one to four carbon atoms or halogeno, R_6 stands for hydrogen or lower alkyl containing from one to four carbon atoms, or the N-oxides of these compounds, as well as their various isomeric forms. This group of compounds may be represented by benzyl 18-O-(2-cyclo-oxa-alkyl)-reserpates or benzyl 18-O-(2-cyclo-oxa-alkyl)-deserpipidates, in which compounds 2-cyclo-oxa-alkyl contains from five to seven atoms as ring members, e.g. benzyl 18-O-(tetrahydro-2-furanyl)-reserpate, benzyl 18-O-(tetrahydro-2-furanyl)-deserpipidate, benzyl 18-O-(tetrahydro-2-pyranyl)-reserpate, benzyl 18-O-(tetrahydro-2-pyranyl)-deserpipidate and the like.

These compounds may be prepared, for example, by alcoholizing a lactone of the formula:

in which R_2 , R_4 , R_5 and R_6 have the previously given meaning, salts or N-oxides thereof, with an alcohol of the formula $Ph-(Z)CH-OH$, in which Ph and Z have the previously given meaning, preferably in the presence of an alcoholysis catalyst, such as an alkali metal, e.g. sodium

and the like, compound of such alcohol, and reacting a resulting compound of the formula:

in which R_2 , R_4 , R_5 , R_6 , Ph and Z have the previously indicated meaning, with a reactive ester of a 2-hydroxy-cyclo-oxa-alkane, which contains at least five atoms as ring members, in the presence of a condensing reagent, or with a cyclo-oxa-alk-2-ene, which contains at least five atoms as ring members, in the presence of an acid condensing reagent, and, if desired, converting a resulting salt into the free compound, and/or, if desired, converting a resulting compound into a salt or an N -oxide thereof.

The alcoholysis of the (16 $\rightarrow$ 18)-lactone of a deserpodic acid compound may be carried out according to known methods. For example, a small amount of an alkali metal, e.g. sodium, potassium and the like, is dissolved in an alcohol of the formula $Ph-(Z)CH-OH$, in which Ph and Z have the previously indicated meaning, or a solution thereof in an inert solvent; the resulting reagent is then reacted with the lactone or a solution thereof. The reaction may proceed under cooling or at room temperature, but may be more readily completed by heating, if necessary, in the atmosphere of an inert gas, e.g. nitrogen.

Treatment of the resulting deserpodic acid ester compound with a reactive ester of a 2-hydroxy-cyclo-oxa-alkane, which contains from five to seven atoms as ring members, particularly a corresponding 2-halogeno-cyclo-oxa-alkane, e.g. 2-chloro-tetrahydrofuran (2-chloro-cyclo-oxapentane), 2-chloro-tetrahydropyran (2-chloro-cyclo-oxahexane) and the like, in the presence of a condensing reagent, especially N,N -dimethylformamide, or with a cyclo-oxa-alk-2-ene, which contains from five to six atoms as ring members, e.g. 2,3-dihydrofuran (cyclo-oxapent-2-ene), 2,3-dihydropyran (cyclo-oxahex-2-ene) and the like, in the presence of an acid condensing reagent, e.g. hydrogen chloride, p-toluenesulfonic acid and the like, is carried out according to previously described methods.

The compounds of the present invention may also be prepared by transesterifying in deserpitate compounds of the formula:

in which R_1' , R_2 , R_3 , R_4 , R_5 and R_6 have the above-given meaning, or an N -oxide thereof, the esterified carboxyl group, having the structural formula $R_1'-O-(O=)C-$, in which R_1 has the above-given meaning, into the esterified carboxyl group $R_1-O-(O=)C-$, in which R_1 has the previously given meaning, by treatment with an alcohol of the formula R_1-OH in the presence of a transesterification agent, and, if desired, carrying out the optional steps.

The transesterification reaction may be carried out, for example, by treating the starting material with an alcohol of the formula R_1-OH , in which R_1 has the above-given meaning, and stands primarily for lower alkyl, particularly lower alkyl containing from one to four carbon atoms, e.g. methyl, ethyl, n-propyl, n-butyl, isobutyl and the like; alcohols of the formula R_1-OH are, therefore, primarily lower alkanols such as methanol, ethanol, n-propanol, n-butanol, isobutanol and the like. Other alcohols of the formula R_1-OH are those, in which R_1 represents lower alkoxy-lower alkyl or tertiary amino-lower alkyl, whereby the lower alkoxy and tertiary amino groups are separated from the hydroxyl group by from two to seven, primarily by from two to three, carbon atoms; such alcohols are, for example, 2-methoxyethanol, 2-ethoxyethanol, 3-methoxypropanol, 2-N,N-dimethylaminoethanol, 2-N,N-diethylaminoethanol and the like.

The reaction is carried out in the presence of a transesterification catalyst, particularly a basic transesterification catalyst. Such catalysts are, for example, alkoxide ions, as, for example, furnished by alkali metal lower alkanolates, e.g. lithium, sodium or potassium methanolate, ethanolate, n-propanolate, n-butanolate or isobutanolate and the like, alkaline earth metal lower alkanolates, e.g. barium or strontium methanolate, ethanolate, n-propanolate, n-butanolate or isobutanolate and the like, or aluminum lower alkanolates, e.g. aluminum methanolate, ethanolate, n-propanolate, isopropanolate, n-butanolate or isobutanolate and the like. The individual alkanolate compounds are employed together with the corresponding lower alkanol used as the transesterification reagent. Other alcohols of the formula R_1-OH , in which R_1 represents, for example, lower alkoxy-lower alkyl or tertiary amino-lower alkyl, may be used in the presence of the corresponding alkali metal, alkaline earth metal or aluminum alcoholates. Other basic transesterification catalysts are, for example, alkali metal cyanides, e.g. potassium cyanide and the like, or strong quaternary ammonium hydroxides, e.g. benzyl-trimethyl-ammonium hydroxide and the like.

Apart from the alcohols of the formula R_1-OH , which may simultaneously serve as diluents, other inert solvents may be used in the above-mentioned reactions; carbocyclic aryl hydrocarbons, e.g. benzene, toluene and the like, are examples of such inert solvents. If necessary, the reaction may be carried out at an elevated temperature, under increased pressure and/or in the atmosphere of an inert gas, e.g. nitrogen.

This method is, therefore, suitable for preparing from compounds of this invention other compounds which are embraced by the generic formula given for the compounds of this invention, and which may not be readily accessible by the other procedures.

The compounds of the present invention may also be obtained by isomerizing in a compound of the formula:

60

65

70

in which R_1 , R_2 , R_3 , R_4 , R_5 and R_6 have the above-given meaning, a salt or an N -oxide thereof, the hydrogen atom attached to the 3-position in the presence of an acid

75

reagent and isolating the desired compound of the formula:

in which R_1 , R_2 , R_3 , R_4 , R_5 and R_6 have the previously given meaning, a salt or an N-oxide thereof, and, if desired, carrying out the optional steps.

Acid reagents used in the above isomerization procedure are more especially lower aliphatic carboxylic acids, such as lower alkanoic acids, e.g. acetic acid, propionic acid and the like, primarily glacial acetic acid, monocyclic carbocyclic aryl sulfonic acids, e.g. p-toluenesulfonic acid and the like or any other suitable acidic reagent or mixtures of acids. Thus, aromatic sulfonic acids are advantageously used together with one of the lower aliphatic carboxylic acids mentioned above; a suitable mixture is, for example, p-toluenesulfonic acid in glacial acetic acid. The reaction may be carried out in the absence or presence of an additional solvent; for example, p-toluenesulfonic acid may be used in the presence of an organic base, e.g. pyridine, collidine and the like, as well as in the presence of another acid, e.g. glacial acetic acid and the like. Isomerization may be effected at room temperature or, if necessary, at an elevated temperature, in an open vessel or under pressure, preferably in the atmosphere of an inert gas, e.g. nitrogen.

Optimum yields in such isomerization reactions may be obtained by removing the desired product from the reaction medium, thus displacing the reaction equilibrium in favor of the product. The removal may be accomplished by separating the product, a salt or an N-oxide thereof from the starting material by exploiting their relative solubilities in solvent systems. For example, the product, a salt or an N-oxide thereof, may be separated from the starting material either by adsorption on a suitable material, such as alumina or paper, and subsequent fractional elution, or by fractional crystallization from a solvent. The starting material separated from the desired product may then be recycled into the isomerization process, enhancing the over-all yield of the reaction.

The intermediates used in the above procedure and having the formula:

in which R_1 , R_2 , R_3 , R_4 , R_5 and R_6 have the previously given meaning, their salts or N-oxides, are new and are intended to be included within the scope of this invention.

Particularly useful are the intermediates of the formula:

in which R_1 represents lower alkyl containing from one to four carbon atoms, lower alkoxy-lower alkyl, in which lower alkoxy contains from one to four carbon atoms and lower alkyl, containing from two to three carbon atoms, separates lower alkoxy from the carboxy group by from two to three carbon atoms, or N,N-di-lower alkyl-amino-lower alkyl, in which lower alkyl of the N,N-di-lower alkyl amino portion contains from one to four carbon atoms and lower alkyl, separating N,N-di-lower alkyl-amino from the carboxy group by two to three carbon atoms, contains from two to three carbons, R_2 represents lower alkyl containing from one to four carbon atoms, R_3 stands for 2-cyclo-oxa-alkyl containing from five to seven atoms as ring members, lower alkyl-substituted 2-cyclo-oxa-alkyl containing from five to seven atoms as ring members, or halogeno-substituted 2-cyclo-oxa-alkyl containing from five to seven atoms as ring members, each of the groups R_4 and R_5 stands for hydrogen, lower alkyl containing from one to four carbon atoms, lower alkoxy containing from one to four carbon atoms or halogeno, and R_6 , attached to one of the positions 5 and 6, stands for hydrogen or lower alkyl containing from one to four carbon atoms, or the N-oxides of these compounds, as well as their various isomeric forms. This group may be represented by lower alkyl 18-O-(2-cyclo-oxa-alkyl)-3-iso-reserpates, in which cyclo-oxa-alkyl contains from five to seven atoms as ring members, e.g. methyl 18-O-(tetrahydro-2-furanyl)-3-iso-reserpate, ethyl 18-O-(tetrahydro-2-furanyl)-3-iso-reserpate, methyl 18-O-(tetrahydro-2-pyranyl)-3-iso-reserpate, ethyl 18-O-(tetrahydro-2-pyranyl)-3-iso-reserpate, n-propyl 18-O-(tetrahydro-2-pyranyl)-3-iso-reserpate, isopropyl 18-O-(tetrahydro-2-pyranyl)-3-iso-reserpate, methyl 18-O-(2-cyclo-oxa-heptyl)-3-iso-reserpate and the like, and by lower alkyl 18-O-(2-cyclo-oxa-alkyl)-3-iso-deserpipidates, in which cyclo-oxa-alkyl contains from five to seven atoms as ring members, e.g. methyl 18-O-(tetrahydro-2-furanyl)-3-iso-deserpipidate, ethyl 18-O-(tetrahydro-2-furanyl)-3-iso-deserpipidate, methyl 18-O-(tetrahydro-2-pyranyl)-3-iso-deserpipidate, ethyl 18-O-(tetrahydro-2-pyranyl)-3-iso-deserpipidate, n-propyl 18-O-(tetrahydro-2-pyranyl)-3-iso-deserpipidate, isopropyl 18-O-(tetrahydro-2-pyranyl)-3-iso-deserpipidate, methyl 18-O-(2-cyclo-oxaheptyl)-3-iso-deserpipidate and the like, as well as by analogous compounds, particularly lower alkyl 18-O-(2-cyclo-oxa-alkyl)-deserpipidate compounds, in which cyclo-oxa-alkyl contains from five to seven atoms as ring members, and in which the 5-position and/or the 6-position may be substituted by lower alkyl, e.g. methyl and the like, or in which the 9-position, the 10-position, the 11-position and/or the 12-position may contain lower alkyl, e.g. methyl and the like, lower alkoxy, e.g. methoxy and the like, or halogen, e.g. chlorine, bromine and the like as substituents, and/or in which the 17-position contains a lower alkoxy substituent other than methoxy, e.g. ethoxy and the like.

The above-mentioned starting material may be prepared by reacting compounds of the formula:

in which R_1 , R_2 , R_3 , R_4 , R_5 and R_6 have the above-given meaning, a salt or an N -oxide thereof, with a reactive ester of a 2-hydroxy-oxa-alkane, which contains at least five atoms as ring members, in the presence of a condensing reagent, or with a cyclo-oxa-alk-2-ene, which contains at least five atoms as ring members, in the presence of an acid condensing reagent, and, if desired, converting a resulting salt into a free base, and/or, if desired, separating a resulting mixture of isomeric compounds into single isomers, and/or, if desired, converting a resulting compound into a salt or an N -oxide thereof.

The reaction of the 3-iso-deserpidate compounds with the above reagents is carried out as previously shown. Reactive esters of 2-hydroxy-cyclo-oxa-alkanes are primarily 2-halogeno-cyclo-alkanes, especially 2-chloro-cyclo-alkanes, which contain from five to seven atoms as ring members, e.g. 2-chloro-tetrahydrofuran (2-chloro-cyclo-oxapentane), 2-chloro-tetrahydropyran (2-chloro-cyclo-oxapentane) and the like; these reagents are used in the presence of a condensing reagent, particularly N,N -dimethylformamide and the like. Cyclo-oxa-alk-2-enes, particularly those which contain from five to six atoms as ring members, e.g. 2,3-dihydrofuran (cyclo-oxapent-2-ene), 2,3-dihydropyran (cyclo-oxahex-2-ene) and the like, are used in the presence of a Lewis acid, particularly of hydrogen halide, e.g. hydrogen chloride and the like, p-toluenesulfonic acid, fluoroboric acid and the like.

The intermediates used in the preparation of the starting materials are known, or, if new, may be prepared according to procedures used for analogous compounds.

Also included within the scope of the invention are compounds of the formula:

in which R_1 , R_2 , R_4 , R_5 and R_6 have the previously given meaning, and R_3' stands for cyclo-dioxa-alkyl or cyclo-oxathia-alkyl, which radicals contain at least five atoms as ring members, and which are attached to the oxygen atoms of the 18-position through one of the carbon atoms adjacent to a ring oxygen atom, salts or N -oxides thereof, as well as the various isomeric forms of these compounds, and process for the preparation of these compounds.

The radicals R_3' contain primarily from five to seven atoms as ring members and, as mentioned hereinbefore, are attached to the oxygen atom of the 18-position through one of the carbon atoms adjacent to a ring oxygen atom. The radicals are unsubstituted or may contain as additional substituents lower aliphatic hydrocarbons, particularly lower alkyl, e.g. methyl, ethyl and the like, or functional groups, particularly halogen atoms, e.g. chlorine, bromine and the like, or other suitable groups. Specific radicals representing R_3' are, for example, 1,3-

dioxalanyl (cyclo-1,3-dioxapentyl) radicals, e.g. 2-(1,3-dioxalanyl) (or 2-cyclo-1,3-dioxapentyl), 4-(1,3-dioxalanyl) (or 2-methyl-4-cyclo-1,3-dioxapentyl) and the like, 1,3-dioxanyl (or cyclo-1,3-dioxahexyl) radicals, e.g. 2-(1,3-dioxanyl) (or 2-cyclo-1,3-dioxahexyl), 4-(1,3-dioxanyl) (or 4-cyclo-1,3-dioxahexyl), 2-methyl-4-(1,3-dioxanyl) (or 2-methyl-4-cyclo-1,3-dioxahexyl), 5-chloro-4-(1,3-dioxanyl) (or 5-chloro-4-cyclo-1,3-dioxahexyl) and the like, 1,4-dioxanyl (or cyclo-1,4-dioxahexyl) radicals, e.g. 2-(1,4-dioxanyl) (or 2-cyclo-1,4-dioxahexyl), 5-methyl-2-(1,4-dioxanyl) (or 5-methyl-2-cyclo-1,4-dioxahexyl), 6-methyl-2-(1,4-dioxanyl) (or 6-methyl-2-cyclo-1,4-dioxahexyl) and the like, cyclo-1,4-dioxaheptyl radicals, e.g. 2-cyclo-1,4-dioxaheptyl and the like, 1,3-oxathianyl (or cyclo-1,3-oxathiapentyl) radicals, e.g. 2-(1,3-oxathianyl) (or 2-cyclo-1,3-oxathiapentyl), 5-(1,3-oxathianyl) (or 5-cyclo-1,3-oxathiapentyl) and the like, 1,3-oxathianyl (or 2-cyclo-1,3-oxathiahexyl) radicals, e.g. 2-(1,3-oxathianyl) (or 2-cyclo-1,3-oxathiahexyl), 6-(1,3-oxathianyl) (or 6-cyclo-1,3-oxathiahexyl), 2-methyl-6-(1,3-oxathianyl) (or 2-methyl-6-cyclo-1,3-oxathiahexyl) and the like, 1,4-oxathianyl (or cyclo-1,4-oxathiahexyl) radicals, e.g. 2-(1,4-oxathianyl) (or 2-cyclo-1,4-oxathiahexyl), 5-methyl-2-(1,4-oxathianyl) (or 5-methyl-2-cyclo-1,4-oxathiahexyl) and the like.

These compounds, as well as their salts and N -oxides, show antihypertensive and/or sedative and tranquilizing effects, and can, therefore, be used to relieve hypertensive conditions and/or states of overactiveness, nervousness and tensions, such as the conditions mentioned hereinabove.

The above compounds may be illustrated by the deserpidate compounds of the formula:

in which R_1 represents lower alkyl containing from one to four carbon atoms, lower alkoxy-lower alkyl, in which lower alkoxy contains from one to four carbon atoms and lower alkyl, containing from two to three carbon atoms, separates lower alkoxy from the carboxyl group by from two to three carbon atoms, or N,N -di-lower alkyl-amino lower alkyl, in which lower alkyl of the N,N -di-lower alkyl-amino portion contains from one to four carbon atoms and lower alkyl, separating N,N -di-lower alkyl-amino from the carboxyl group by two to three carbon atoms, contains from two to three carbons, R_2 represents lower alkyl containing from one to four carbon atoms, R_3' stands for 2-(1,4-dioxanyl) (or 2-cyclo-1,4-dioxahexyl), lower alkyl-substituted 2-(1,4-dioxanyl) (or lower alkyl-substituted 2-cyclo-1,4-dioxahexyl), halogeno-substituted 2-(1,4-dioxanyl) (or halogeno-substituted 2-cyclo-1,4-dioxahexyl), 2-(1,4-oxathianyl) (or 2-cyclo-1,4-oxathiahexyl), lower alkyl-substituted 2-(1,4-oxathianyl) (or lower alkyl-substituted 2-cyclo-1,4-oxathiahexyl), or halogeno-substituted 2-(1,4-oxathianyl) (or halogeno-substituted 2-cyclo-1,4-oxathiahexyl), each of the groups R_4 and R_5 stands for hydrogen, lower alkyl containing from one to four carbon atoms, lower alkoxy containing from one to four carbon atoms or halogeno, and R_6 attached to one of the positions 5 and 6, stands for hydrogen or lower alkyl containing from one to four carbon atoms, therapeutically acceptable mineral acid addition salts or the N -oxides of these compounds, as well as their various isomeric forms.

This group may be illustrated by the reserpate compounds of the formula:

in which R_1 represents lower alkyl containing from one to four carbon atoms, and X stands for oxygen or sulfur, or N -oxides of such compounds. Members of this group are, for example, methyl 18-O-[2-(1,4-dioxanyl)]-reserpate, ethyl 18-O-[2-(1,4-dioxanyl)]-reserpate, n-propyl 18-O-[2-(1,4-dioxanyl)]-reserpate, n-butyl 18-O-[2-(1,4-oxathianyl)]-reserpate, methyl 18-O-[2-(1,4-oxathianyl)]-reserpate, ethyl 18-O-[2-(1,4-oxathianyl)]-reserpate, n-propyl 18-O-[2-(1,4-oxathianyl)]-reserpate, isopropyl 18-O-[2-(1,4-oxathianyl)]-reserpate and the like, as well as N -oxides of such compounds, whereby these compounds may be present in various isomeric forms.

Another outstanding group of compounds are the deserpide compounds of the formula:

in which R_1 represents lower alkyl containing from one to four carbon atoms, and X stands for oxygen or sulfur, or N -oxides of such compounds. This group may be illustrated, for example, by methyl 18-O-[2-(1,4-dioxanyl)]-deserpide, ethyl 18-O-[2-(1,4-dioxanyl)]-deserpide, isopropyl 18-O-[2-(1,4-dioxanyl)]-deserpide, n-butyl 18-O-[2-(1,4-dioxanyl)]-deserpide, methyl 18-O-[2-(1,4-oxathianyl)]-deserpide, ethyl 18-O-[2-(1,4-oxathianyl)]-deserpide, n-propyl 18-O-[2-(1,4-oxathianyl)]-deserpide, isopropyl 18-O-[2-(1,4-oxathianyl)]-deserpide and the like, as well as N -oxides of such compounds, and the various isomeric forms of these compounds.

Additional compounds, which illustrate the above group, are lower alkoxy-lower alkyl, in which lower alkoxy contains from one to four carbon atoms and lower alkyl, containing from two to three carbon atoms, separates lower alkoxy from the carboxy group by from two to three carbon atoms, e.g. 2-methoxyethyl, 2-ethoxyethyl, 3-methoxypropyl and the like, 18-O- R_3 '-reserpate or 18-O- R_3 '-deserpide, in which R_3' represents 2-(1,4-dioxanyl) or 2-(1,4-oxathianyl), N,N -di-lower alkyl-amino-lower alkyl, in which lower alkyl of the N,N -di-lower alkyl-amino group contains from one to four carbon atoms, and lower alkyl, separating the amino group from the carboxy group by from two to three carbon atoms, contains from two to three carbon atoms, e.g. 2- N,N -dimethylaminoethyl, 2- N,N -diethylaminoethyl, 3- N,N -dimethylaminopropyl and the like, 18-O- R_3 '-reserpate or 18-O- R_3 '-deserpide, in which R_3' represents 2-(1,4-dioxanyl) or 2-(1,4-oxathianyl), or lower alkyl, e.g. methyl, ethyl, n-propyl and the like, 5-methyl-18-O- R_3 '-reserpate, lower alkyl 5-methyl-18-O- R_3 '-deserpide, lower alkyl 6-methyl-18-O- R_3 '-reserpate, lower alkyl 6-methyl-18-O- R_3 '-deserpide, lower alkyl 9-methyl-18-O- R_3 '-deserpide, lower alkyl 11-methyl-18-O- R_3 '-deserpide, lower alkyl 9-methoxy-18-O- R_3 '-deserpide, lower alkyl 10-methoxy-18-O- R_3 '-deserpide,

lower alkyl 10-methoxy-18-O- R_3 '-reserpate, lower alkyl 11-ethoxy-18-O- R_3 '-deserpide, lower alkyl 11-isopropoxy-18-O- R_3 '-deserpide, lower alkyl 12-methoxy-18-O- R_3 '-deserpide, lower alkyl 10-chloro-18-O- R_3 '-deserpide, lower alkyl 10-bromo-18-O- R_3 '-reserpate, lower alkyl 10-bromo-18-O- R_3 '-deserpide, lower alkyl 11-methylmercapto-18-O- R_3 '-deserpide, lower alkyl 11-ethylmercapto-18-O- R_3 '-deserpide, lower alkyl 17-desmethoxy-17-ethoxy-18-O- R_3 '-deserpate and the like, in which compounds R_3' represents 2-(1,4-dioxanyl) or 2-(1,4-oxathianyl), their N -oxides and various isomeric forms.

The compounds described hereinbefore may be prepared by treating a compound of the formula:

in which R_1 , R_2 , R_4 , R_5 and R_6 have the previously given meaning, or an N -oxide thereof, with a reactive ester of 30 a hydroxy-cyclo-dioxa-alkane or a hydroxy-cyclo-oxathia-alkane, which contains at least five atoms as ring members, and in which the hydroxyl group is attached to one of the carbon atoms adjacent to a ring oxygen atom, in the presence of a condensing reagent, or converting in 35 a compound of the formula:

in which R_2 , R_3' , R_4 , R_5 and R_6 have the previously given meaning, a salt or an N -oxide thereof, the free carboxyl group of the formula $\text{HO}-(\text{O}=\text{)C-}$ into an esterified carboxyl group of the formula $\text{R}_1-\text{O}-(\text{O}=\text{)C-}$, in which R_1 has the previously given meaning, or converting in a compound of the formula:

in which R_2 , R_3' , R_4 , R_5 and R_6 have the previously given meaning, and R_1' represents lower alkyl, lower 70 alkoxy-lower alkyl, tertiary amino-lower alkyl, or a group of the formula $\text{Ph}-(\text{Z})\text{CH}-$, in which Ph and Z have the previously given meaning, or an N -oxide thereof, the radical R_1' into the desired radical R_1 by transesterification with an alcohol of the formula R_1-OH , in which R_1 75 has the previously given meaning, in the presence of a

transesterification reagent, or isomerizing in a compound of the formula:

in which R_1 , R_2 , R_3' , R_4 , R_5 and R_6 have the previously given meaning, a salt or an N-oxide thereof, the hydrogen atom attached to the 3-position in the presence of an acid reagent, and isolating the desired compound having the previously given formula, and, if desired, converting a resulting salt into the free compound, and/or, if desired, separating a mixture of isomeric compounds into the single compounds, and/or, if desired, converting a resulting compound into a salt or into an N-oxide thereof.

The reactions in the above procedures are carried out according to the general methods given hereinbefore. For example, a reactive ester of a hydroxy-cyclo-dioxa-alkane or a hydroxy-cyclo-oxathia-alkane is an ester with one of the previously mentioned acids, particularly with a hydrohalic acid, e.g. hydrochloric, hydrobromic acid and the like; specific reagents are, for example, halogeno-1,3-dioxalanes (or halogeno-cyclo-1,3-dioxapentanes), in which halogen is attached to one of the carbon atoms adjacent to the ring oxygen atoms, e.g. 2-chloro-1,3-dioxalane (or 2-chloro-cyclo-1,3-dioxapentane), 4-chloro-1,3-dioxalane (or 4-chloro-cyclo-1,3-dioxapentane) and the like, halogeno-1,3-dioxanes (or halogeno-cyclo-1,3-dioxahexanes), in which halogen is attached to one of the carbon atoms adjacent to the ring oxygen atoms, e.g. 2-chloro-1,3-dioxane (or 2-chloro-cyclo-1,3-dioxahexane), 4-chloro-1,3-dioxane (or 4-chloro-cyclo-1,3-dioxahexane) and the like, halogeno-1,4-dioxanes (or halogeno-cyclo-1,4-dioxahexanes), in which halogen is attached to one of the carbon atoms adjacent to the ring oxygen atoms, e.g. 2-chloro-1,4-dioxane (or 2-chloro-cyclo-1,4-dioxahexane), 2-chloro-5-methyl-1,4-dioxane (or 2-chloro-5-methyl-cyclo-1,4-dioxahexane) and the like, halogeno-1,3-oxathialanes (or halogeno-cyclo-1,3-oxathiapentanes), in which the halogen atom is attached to a carbon atom adjacent to the ring oxygen atom, e.g. 2-chloro-1,3-oxathiane (or 2-chloro-cyclo-1,3-oxathiapentane), 5-chloro-1,3-oxathialane (or 5-chloro-cyclo-1,3-oxathiapentane) and the like, halogeno-1,3-oxathiahexanes (or halogeno-cyclo-1,3-oxathiahexane), in which the halogen atom is attached to a carbon atom adjacent to the ring oxygen atom, e.g. 2-chloro-1,3-oxathiane (or 2-chloro-cyclo-1,3-oxathiahexane), 6-chloro-1,3-oxathiane (or 6-chloro-cyclo-1,3-oxathiahexane) and the like, or halogeno-1,4-oxathianes (or halogeno-cyclo-1,3-oxathiahexanes), in which the halogen atom is attached to a carbon atom adjacent to the ring oxygen atom, e.g. 2-chloro-1,4-oxathiane (or 2-chloro-cyclo-1,4-oxathiahexane), 2-chloro-5-methyl-1,4-oxathiane (or 2-chloro-5-methyl-cyclo-1,4-oxathiahexane) and the like. These reagents are used in the presence of a condensing reagent, particularly N,N-dimethylformamide and the like.

Or, the free carboxyl group in a deserpodic acid compound of the previously given structural formula may be converted into the desired esterified carboxyl group by treatment with a diazo compound of the formula R_1N_2 , in which R_1 has the previously given meaning, particularly with a lower diazo-alkane, e.g. diazomethane, diazoethane, 1-diazopropane and the like, with a lower alkoxy-diazo-lower alkane, e.g. 2-methoxy-diazoethane, 2-ethoxy-diazoethane, 3-methoxy-1-diazopropane and the like, or with an N,N-di-lower alkyl-amino-lower diazoalkane, e.g.

2-N,N-dimethylamino-diazoethane and the like. These reagents may be used as previously shown.

The starting materials used in this modification of the procedure having the formula:

in which R_2 , R_3' , R_4 , R_5 and R_6 have the previously given meaning, salts or N-oxides thereof, are new and are intended to be included within the scope of the invention. Particularly useful are the deserpodic acid compounds of the formula:

in which R_2 represents lower alkyl containing from one to four carbon atoms, R_3' represents 2-cyclo-1,4-dioxa-hexyl or 2-cyclo-1,4-oxathiahexyl or the corresponding lower alkyl-substituted or halogeno-substituted radicals, each of the groups R_4 and R_5 stands for hydrogen, lower alkyl containing from one to four carbon atoms, lower alkoxy containing from one to four carbon atoms, lower alkyl-mercapto containing from one to four carbon atoms or halogeno, and R_6 , attached to one of the positions 5 and 6, stands for hydrogen or lower alkyl, or N-oxides of such compounds, as well as the various possible isomeric forms thereof. Specific compounds of this group are 18-O-[2-(1,4-dioxanyl)]-reserpic acid, 18-O-[2-(1,4-oxathianyl)]-reserpic acid, 18-O-[2-(1,4-dioxanyl)]-deserpodic acid, 18-O-[2-(1,4-oxathianyl)]-deserpodic acid, 6-methyl-18-O-[2-(1,4-dioxanyl)]-reserpic acid, 10-methoxy-18-O-[2-(1,4-dioxanyl)]-reserpic acid, 12-methoxy-18-O-[2-(1,4-dioxanyl)]-deserpodic acid, 10-chloro-18-O-[2-(1,4-dioxanyl)]-deserpodic acid, 10-bromo-18-O-[2-(1,4-dioxanyl)]-deserpodic acid, 17-desmethoxy-17-ethoxy-18-O-[2-(1,4-dioxanyl)]-reserpic acid and the like.

These starting materials may be obtained according to the methods previously outlined for the preparation of analogous deserpodic acid compounds.

Transesterification of the esterified carboxyl group of the formula $R_1'-O-(O=)C-$, in which R_1' has the previously given meaning, into the desired esterified carboxyl group of the formula $R_1-O-(O=)C-$, in which R_1 has the previously given meaning, may be carried out as previously shown; for example, the compound previously shown by way of the above-depicted structural formula, when reacted with an alcohol of the formula R_1-OH , in which R_1 has the previously given meaning, in the presence of a trans-esterification catalyst, such as, for example, an alkali metal compound of the alcohol R_1-OH , yields an ester compound, in which the esterified carboxyl group has the formula $R_1-O-(O=)C-$, in which R_1 has the previously given meaning. Alcohols of the above-given formula are particularly lower alkanols, e.g. methanol, ethanol, n-propanol, isopropanol, n-butanol and the like, lower alkoxy-lower alkanols, e.g. 2-methoxyethanol, 2-ethoxyethanol, 3-methoxypropanol and the like, or N,N-di-lower alkyl-amino-lower alkanols, e.g. 2-N,N-dimethylaminoethanol and the like; trans-

esterification catalysts may be, for example, the alkali metal, e.g. lithium, sodium, potassium and the like, compounds of these alcohols, or other suitable basic catalysts, such as those mentioned hereinbefore, e.g. potassium cyanide, benzyl trimethyl ammonium hydroxide and the like. The reaction is carried out as previously shown.

Starting materials, which are used in the above procedures and have the previously given structural formula, in which R_2 , R_3' , R_4 , R_5 and R_6 have the aforementioned meaning, and R_1' stands for the group of the formula $\text{Ph}-(\text{Z})\text{CH}-$, in which Ph and Z have the above-given meaning, are new and are intended to be included within the scope of the invention. Particularly useful are the compounds of the formula:

in which R_2 represents lower alkyl containing from one to four carbon atoms, R_3' stands for 2-(1,4-dioxanyl) (or 2-cyclo-1,4-dioxahexyl), lower alkyl-substituted 2-(1,4-dioxanyl) (or lower alkyl-substituted 2-cyclo-1,4-dioxahexyl), halogeno-substituted 2-(1,4-dioxanyl) (or halogeno-substituted 2-cyclo-1,4-dioxahexyl), 2-(1,4-oxathianyl) (or 2-cyclo-1,4-oxathiahexyl), lower alkyl-substituted 2-(1,4-oxathianyl) (or lower alkyl-substituted 2-cyclo-1,4-oxathiahexyl), or halogeno-substituted 2-(1,4-oxathianyl) (or halogeno-substituted 2-cyclo-1,4-oxathiahexyl), each of the groups R_4 and R_5 stands for hydrogen, lower alkyl containing from one to four carbon atoms, lower alkoxy containing from one to four carbon atoms or halogeno, and R_6 , attached to one of the positions 5 and 6, stands for hydrogen or lower alkyl containing from one to four carbon atoms, acid addition salts or the N-oxides of these compounds, as well as their various isomeric forms.

This group of compounds may be represented by benzyl 18-O- R_3' -reserpate and benzyl 18-O- R_3' -deserpipidate, in which R_3' stands for 2-(1,4-dioxanyl) or 2-(1,4-oxathianyl), or N-oxides thereof; specific compounds are, for example, benzyl 18-O-[2-(1,4-dioxanyl)]-reserpate, benzyl 18-O-[2-(1,4-oxathianyl)]-reserpate, benzyl 18-O-[2-(1,4-dioxanyl)]-deserpipidate, benzyl 18-O-[2-(1,4-oxathianyl)]-deserpipidate and the like.

These compounds may be prepared, for example, by alcoholizing a lactone of the formula:

in which R_2 , R_4 , R_5 and R_6 have the previously given meaning, salts or N-oxides thereof, with an alcohol of the formula $\text{Ph}-(\text{Z})\text{CH}-\text{OH}$, in which Ph and Z have the previously given meaning, preferably in the presence of an alcoholysis catalyst, such as an alkali metal, e.g.

sodium and the like, compound of such alcohol, and recating a resulting compound of the formula:

in which R_2 , R_4 , R_5 , R_6 , Ph and Z have the previously given meaning, with the reactive ester of a hydroxy-cyclo-dioxa-alkane or of a hydroxy-cyclo-oxathia-alkane, which contain at least five atoms as ring members, and in which the hydroxyl group is attached to one of the carbon atoms adjacent to a ring oxygen, in the presence of a condensing reagent, and, if desired, converting a resulting compound into a salt or an N-oxide thereof.

The alcoholysis of the lactone can be performed as previously shown; a deserpipidate compound reacts with the reactive ester of a hydroxy-cyclo-dioxa-alkane or a hydroxy-cyclo-oxathia-alkane according to the above-described method, particularly in the presence of N,N-dimethylformamide as a condensing reagent.

Isomerization of 3-iso-deserpipidate compounds having the previously shown structural formula may be carried out as previously shown; acids, such as glacial acetic acid, p-tolene sulfonic acid or a mixture of such acids, are suitable isomerization reagents.

The starting materials used in the latter modification, which has the previously given structural formula, are new and are intended to be included within the scope of the invention. Especially valuable starting materials are the compounds of the formula:

in which R_1 represents lower alkyl containing from one to four carbon atoms, lower alkoxy-lower alkyl, in which lower alkoxy contains from one to four carbon atoms and lower alkyl, containing from two to three carbon atoms, separates lower alkoxy from the carboxy group by from two to three carbon atoms, or N,N-di-lower alkyl-amino-lower alkyl, in which lower alkyl of the N,N-di-lower alkyl amino portion contains from one to four carbon atoms and lower alkyl, separating N,N-di-lower alkyl-amino from the carboxy group by two to three carbon atoms, contains from two to three carbons, R_2 represents lower alkyl containing from one to four carbon atoms, R_3' stands for 2-(1,4-dioxanyl) (or 2-cyclo-1,4-dioxahexyl), lower alkyl-substituted 2-(1,4-dioxanyl) (or lower alkyl-substituted 2-cyclo-1,4-dioxahexyl), halogeno-substituted 2-(1,4-dioxanyl) (or halogeno-substituted 2-cyclo-1,4-dioxahexyl), 2-(1,4-oxathianyl) (or 2-cyclo-1,4-oxathiahexyl), lower alkyl-substituted 2-(1,4-oxathianyl) (or lower alkyl-substituted 2-cyclo-1,4-oxathiahexyl), or halogeno-substituted 2-(1,4-oxathianyl) (or halogeno-substituted 2-cyclo-1,4-oxathianyl), each of the groups R_4 and R_5 stands for hydrogen, lower alkyl containing from one to four carbon atoms, lower alkoxy containing from one to four carbon atoms or halogeno, and R_6 , attached to one of the positions 5 and 6, stands for hydrogen or lower alkyl containing from one to four carbon atoms, acid addition salts or the N-oxides of these compounds, as well as their various isomeric forms.

salts or the N-oxides of these compounds, as well as their various isomeric forms.

This group of compounds may be represented by lower alkyl 18-O-R₃-3-iso-reserpate or lower alkyl 18-O-R₃-iso-deserpdate, in which R₃ stands for 2-(1,4-dioxanyl) or 2-(1,4-oxathianyl), or N-oxides thereof. Specific compounds are, for example, methyl 18-O-[2-(1,4-dioxanyl)]-3-iso-reserpate, ethyl 18-O-[2-(1,4-dioxanyl)]-3-iso-reserpate, n-propyl 18-O-[2-(1,4-dioxanyl)]-3-iso-reserpate, methyl 18-O-[2-(1,4-oxathianyl)]-3-iso-reserpate, methyl 18-O-[2-(1,4-dioxanyl)]-3-iso-deserpdate, methyl 18-O-[2-(1,4-oxathianyl)]-3-iso-deserpdate and the like.

These compounds may be prepared, for example, by reacting a compound of the formula:

in which R₁, R₂, R₄, R₅ and R₆ have the above-given meaning, or an N-oxide thereof, with the reactive ester of a hydroxy-cyclo-dioxa-alkane or of a hydroxy-cyclo-oxathia-alkane, which contain at least five atoms as ring members, and in which the hydroxyl group is attached to one of the carbon atoms adjacent to a ring oxygen atom, in the presence of a condensing reagent, and, if desired, converting a resulting compound into a salt or an N-oxide thereof.

The reaction of the deserpdate compound with the ester of a hydroxy-cyclo-dioxa-alkane or a hydroxy-cyclo-oxathia-alkane can be carried out according to the previously described method, particularly in the presence of N,N-dimethylformamide as a condensing reagent.

The compounds prepared according to the process of this invention may be obtained in the form of the free bases or the salts thereof. A salt may be converted into the free base by reacting the former with an alkaline reagent, such as, for example, aqueous silver oxide, aqueous ammonia, or any other suitable alkaline reagent. A free base may be converted into its therapeutically useful acid addition salts by reaction with one of the acids mentioned hereinbefore; such reaction may be carried out, for example, by treating a solution of the base in a solvent, such as a lower alkanol, e.g. methanol, ethanol, propanol, isopropanol and the like, with the appropriate acid or a solution thereof, and isolating the formed salt.

N-oxides of the compounds of the present invention may be formed according to known methods; for example, the resulting deserpdate compound, preferably a solution thereof in an inert solvent, may be reacted with an N-oxidizing reagent, such as, for example, hydrogen peroxide, ozone, persulfuric acid, or more especially, organic peracids, such as organic percarboxylic acids, e.g. peracetic, perbenzoic, monoperphthalic acid and the like, or per-sulfonic acids, e.g. p-toluenesulfonic acid and the like. Inert solvents are, for example, monocyclic carboxylic aryl hydrocarbons, e.g. benzene, toluene and the like, halogenated lower alkanes, e.g. chloroform, ethylene chloride and the like, lower alkanols, e.g. methanol, ethanol and the like, or any other suitable solvent. In the N-oxidation reaction an excess of the oxidation reagent and/or an increase in temperature should be avoided in order to prevent oxidative degradation.

Depending on the form of starting materials used in the formation of the compounds of the present invention, the latter may be obtained in the form of different isomers. Thus, racemic or optically active deserpatic acid derivatives may be used as starting materials whereby the latter is preferably used in the optically active form, par-

ticularly when derived from natural sources. Resulting racemates may be resolved into the optically active forms, the laevo-rotatory l-form and the dextro-rotatory d-form. Resolution procedures may be carried out according to known methods suitable for the separation of racemates. For example, to a solution of the free base of a racemate (a d, l-compound) in a solvent, such as a lower alkanol, e.g. methanol, ethanol, isopropanol and the like, a lower alkanone, e.g. acetone, ethyl methyl ketone and the like, or any other suitable solvent, or a mixture of solvents, is added one of the optically active forms of an acid containing an asymmetric carbon atom, or a solution thereof, for example, in the same lower alkanol, lower alkanone, other solvent, or solvent mixture mentioned hereinabove. Salts, which are formed by the optically active forms of the base with the optically active form of the acid may then be isolated, primarily on the basis of their different solubilities. Useful as optically active forms of salt-forming acids having an asymmetric carbon atom, are, for example, the d-tartaric acid (L-tartaric acid) and the l-tartaric acid (D-tartaric acid), as well as the optically active forms of dibenzoyl tartaric, di-p-tolyl-tartaric, malic, mandelic, 10-camphor sulfonic acid, quinic acid and the like. The free and optically active base may be obtained from a resulting salt according to methods known for the conversion of a salt into a base as, for example, is outlined hereinbefore. An optically active base may be converted into a therapeutically useful acid addition salt with one of the acids mentioned hereinbefore, or may be converted into an N-oxide described hereinbefore. The optically active forms may also be isolated by biochemical methods.

Or, by reacting a deserpdate compound with a cyclo-alk-2-ene as mentioned hereinbefore, two isomeric compounds may be formed, which may be separated on the basis of differences of physico-chemical properties, e.g. solubility, adsorbability and the like.

The invention also comprises any modification of the process wherein a compound obtainable as an intermediate at any stage of the process is used as starting material and the remaining step(s) of the process is (are) carried out. It also includes any new intermediates, which may be formed in one of the procedures outlined hereinbefore.

In the process of this invention such starting materials are preferably used which lead to final products mentioned in the beginning as preferred embodiments of the invention.

The present application is a continuation-in-part application of my applications Serial No. 837,351, filed September 1, 1959, and Serial No. 837,352, filed September 1, 1959, each of which in turn is a continuation-in-part application of my application Serial No. 818,511, filed June 8, 1959, which in turn is a continuation-in-part of my application Serial No. 803,360, filed April 1, 1959, which in turn is a continuation-in-part of my application Serial No. 793,959, filed February 18, 1959, all now abandoned.

The following examples illustrate the invention and are not to be construed as being limitations thereon. Temperatures are given in degrees centigrade.

Example 1

1 g. of methyl reserpate is suspended in 25 ml. of 2,3-dihydropyran and 7 drops of concentrated aqueous hydrochloric acid (37 percent) is added, while agitating. The flask is closed with a glass stopper, shaken and then allowed to stand for three days at room temperature. 10 ml. of aqueous ammonia (28 percent) is added while stirring, and an excess of benzene is then given to the reaction mixture to form two layers. The organic layer is separated, dried over sodium sulfate and evaporated under reduced pressure. The residue is dissolved in acetone, the solvent is evaporated and the residue is again taken up in acetone, whereupon crystals are formed which are filtered off. The mother liquor is diluted with ether and a second crop of crystals are obtained which are

combined with the first crystallization product. The methyl 18-O-(tetrahydro-2-pyranyl)-reserpate melts at 262-265° (decomposition); yield: 0.29 g.

Example 2

To a mixture of 1 g. of methyl reserpate and 15 ml. of 2,3-dihydropyran is added 35 ml. of benzene, which has been saturated at room temperature with gaseous hydrogen chloride. The reaction vessel is then closed, thoroughly shaken and allowed to stand for two hours at room temperature to form a complete solution. 20 ml. of 10 percent aqueous sodium hydroxide is added while shaking, the benzene layer is separated, washed once with water and dried over sodium sulfate. The solvent is evaporated under reduced pressure and ether is added to the residue. The crystalline material is filtered off and washed with ether to yield the methyl 18-O-(tetrahydro-2-pyranyl)-reserpate, M.P. 265-267°; yield: 0.55 g.

The resulting product is identical in every respect with the compound obtained according to the procedure of Example 1.

Example 3

To 5 g. of n-propyl reserpate in 100 ml. of 2,3-dihydropyran is added 100 ml. of benzene, which has been saturated with hydrogen chloride at room temperature; the reaction mixture is placed in a flask and the closed flask is allowed to stand at room temperature for about thirty minutes. 80 ml. of a cold 10 percent aqueous solution of sodium hydroxide, containing a small amount of ammonia, is added while shaking. The benzene layer is separated, washed twice with ice water, containing a small amount of ammonia, dried over sodium sulfate, filtered and evaporated under reduced pressure. The oily residue is dissolved in petroleum ether and crystallizes after cooling. The crystalline material is filtered off, and dissolved in methylene chloride; the solution is filtered through a column containing magnesia-silica gel, the solvent is evaporated, and the residue is crystallized from a mixture of petroleum ether and ether to yield 3.49 g. of n-propyl 18-O-(tetrahydro-2-pyranyl)-reserpate, M.P. 190-192°.

The starting material may be prepared as follows: The gaseous n-diazopropane is distilled from its ether solution into a suspension of 20 g. of reserpic acid in a 1:1 mixture of chloroform and ethanol. Any excess of n-diazopropane is decomposed with acetic acid, the solvents are evaporated under reduced pressure and the residue is poured into 800 ml. of water containing 20 ml. of concentrated aqueous ammonia. A white crystalline precipitate is obtained, which is washed with water to yield the n-propyl reserpate, M.P. 164-166°.

Example 4

To 1 g. of 2-methoxyethyl reserpate in 25 ml. of 2,3-dihydropyran is added 25 ml. of benzene, which has been saturated at room temperature with hydrogen chloride; the mixture is allowed to stand at room temperature for two hours. To the homogeneous solution is then added 20 ml. of 10 percent aqueous sodium hydroxide while shaking. The organic layer is separated, washed twice with water containing a few drops of concentrated aqueous ammonia and then dried over sodium sulfate. A yellow oil is obtained after evaporating the solvent under reduced pressure. It is dissolved in acetone; petroleum ether is added to this solution, the supernatant liquid is decanted from the gummy precipitate, which is allowed to stand overnight in the refrigerator. The gel-like solid is dried on a filter to yield a tan powder, representing 2-methoxyethyl 18-O-(tetrahydro-2-pyranyl)-reserpate, M.P. 78-85°.

The starting material may be prepared as follows: To a mixture of 226 g. of a 33 percent aqueous solution of 2-methoxyethylamine and 150 ml. of diethyl ether, kept at 5° to 10° in an ice bath, is added dropwise 54 g. of ethyl chloroformate. 100 g. of a cold 40% aqueous solu-

tion of sodium hydroxide and a second portion of 54 g. of ethyl chloroformate are given to the mixture, which is stirred for one hour. The ether layer is separated, the aqueous phase is extracted with 100 ml. of diethyl ether, and the two ether solutions are combined and dried over potassium carbonate. The solvent is evaporated under reduced pressure and the ethyl N-(2-methoxyethyl)-carbamate is distilled at 105-106°/17-20 mm.

To a solution of 33 g. of ethyl N-(2-methoxyethyl)-carbamate in 200 ml. of diethyl ether are added 25 g. of cracked ice and a solution of 81 g. of sodium nitrite in 125 ml. of water. While keeping the temperature below 15°, 150 g. of 35% aqueous nitric acid is added carefully over a period of one hour. The ether layer is separated, washed with water and aqueous potassium carbonate and then dried over potassium carbonate. The residue, obtained after evaporation of the solvent under reduced pressure, represents the ethyl N-(2-methoxyethyl)-N-nitroso-carbamate, which is used without further purification.

A gently refluxing solution of 5 g. of potassium hydroxide in 15 g. of methanol and 150 ml. of diethyl ether is treated with a solution of 15.5 g. of ethyl N-(2-methoxyethyl)-N-nitroso-carbamate in 50 ml. of diethylether, which is added dropwise over a period of one hour. After refluxing for 5 minutes, 100 ml. of water is added and the yellow ether solution, containing the 2-methoxydiazoethane, is separated.

The above ether solution of 2-methoxy-diazoethane is reacted with small portions of a slurry of reserpic acid in methanol until no further reaction can be observed. A few drops of acetic acid are added, the solution is evaporated under reduced pressure and the residual oil is dissolved in ethyl acetate. Upon addition of petroleum ether a precipitate is formed, which is filtered off, dissolved in methylene chloride, which solution is washed with aqueous ammonia and filtered through a small column containing a diatomaceous earth. The residue, obtained after evaporation of the solvent, is crystallized from ethyl acetate to yield the 2-methoxyethyl reserpate, M.P. 183-185°.

Other deserpidates which may be prepared according to the previously given procedure by replacing the starting material by other intermediates are, for example,

- 45 2-ethoxyethyl 18-O-(tetrahydro-2-pyranyl)-reserpate,
- 2-n-propyloxyethyl 18-O-(tetrahydro-2-pyranyl)-reserpate,
- 2-isopropoxyethyl 18-O-(tetrahydro-2-pyranyl)-reserpate,
- 3-methoxypropyl 18-O-(tetrahydro-2-pyranyl)-reserpate,
- 50 2-methoxyethyl 18-O-(tetrahydro-2-pyranyl)-deserpipate,
- 2-ethoxyethyl 18-O-(tetrahydro-2-pyranyl)-deserpipate,
- 2-methoxyethyl 5-methyl-18-O-(tetrahydro-2-pyranyl)-reserpate,
- 2-methoxyethyl 5-methyl-18-O-(tetrahydro-2-pyranyl)-deserpipate,
- 55 2-methoxyethyl 6-methyl-18-O-(tetrahydro-2-pyranyl)-reserpate,
- 2-methoxyethyl 9-methyl-18-O-(tetrahydro-2-pyranyl)-deserpipate,
- 60 2-methoxyethyl 11-methyl-18-O-(tetrahydro-2-pyranyl)-deserpipate,
- 2-methoxyethyl 9-methoxy-18-O-(tetrahydro-2-pyranyl)-deserpipate,
- 2-methoxyethyl 10-methoxy-18-O-(tetrahydro-2-pyranyl)-deserpipate,
- 65 2-methoxyethyl 10-methoxy-18-O-(tetrahydro-2-pyranyl)-reserpate,
- 2-methoxyethyl 12-methoxy-18-O-(tetrahydro-2-pyranyl)-deserpipate,
- 70 2-methoxyethyl 11-ethoxy-18-O-(tetrahydro-2-pyranyl)-deserpipate,
- 2-methoxyethyl 11-n-propyloxy-18-O-(tetrahydro-2-pyranyl)-deserpipate,
- 2-ethoxyethyl 11-isopropoxy-18-O-(tetrahydro-2-pyranyl)-deserpipate,
- 75

31

- 2-methoxyethyl 11-n-butyloxy-18-O-(tetrahydro-2-pyranyl)-deserpdate,
 2-methoxyethyl 10,11-methylenedioxy-18-O-(tetrahydro-2-pyranyl)-deserpdate,
 2-methoxyethyl 10-benzyloxy-18-O-(tetrahydro-2-pyranyl)-deserpdate,
 2-ethoxyethyl 11-benzyloxy-18-O-(tetrahydro-2-pyranyl)-deserpdate,
 2-methoxyethyl 11-methylmercapto-18-O-(tetrahydro-2-pyranyl)-deserpdate,
 3-methoxypropyl 11-ethylmercapto-18-O-(tetrahydro-2-pyranyl)-deserpdate,
 2-methoxyethyl 10-chloro-18-O-(tetrahydro-2-pyranyl)-deserpdate,
 2-methoxyethyl 10-bromo-18-O-(tetrahydro-2-pyranyl)-deserpdate,
 2-methoxyethyl 17-desmethoxy-17-ethoxy-18-O-(tetrahydro-2-pyranyl)-reserpate,
 2-methoxyethyl 17-desmethoxy-17-n-propyloxy-18-O-(tetrahydro-2-pyranyl)-reserpate,
 2-methoxyethyl 17-desmethoxy-17-isopropyloxy-18-O-(tetrahydro-2-pyranyl)-reserpate
 and the like.

Example 5

To a solution of 4.3 g. of crude methyl deserpdate and 4.6 ml. of 2,3-dihydropyran in 40 ml. of acetone is gradually added 2.82 g. of p-tolene sulfonic acid in 12 ml. of acetone while stirring. The solution is agitated for an additional thirty minutes, ethyl acetate is added and the resulting solution is washed twice with 10 percent aqueous sodium hydroxide and then with water. The organic layer is dried over sodium sulfate, the solvent is removed under reduced pressure and the residue is crystallized from a mixture of ethyl acetate and petroleum ether. The resulting methyl 18-O-(tetrahydro-2-pyranyl)-deserpdate is recrystallized from ethyl acetate, M.P. 255-257°; yield: 0.57 g.

Methyl deserpdate may be replaced by other lower alkyl deserpdates in the above example, and compounds, such as ethyl 18-O-(tetrahydro-2-pyranyl)-deserpdate, n-propyl 18-O-(tetrahydro-2-pyranyl)-deserpdate, isopropyl 18-O-(tetrahydro-2-pyranyl)-deserpdate, n-butyl 18-O-(tetrahydro-2-pyranyl)-deserpdate, isobutyl 18-O-(tetrahydro-2-pyranyl)-deserpdate and the like, are formed upon treatment with 2,3-dihydropyran according to the above procedure.

Example 6

A mixture of 1.0 g. of 2-dimethylaminoethyl reserpate and 25 ml. of 2,3-dihydropyran, when treated with 25 ml. of benzene, which has been saturated with hydrogen chloride, according to the procedure outlined in Example 2, yields the desired 2-dimethylaminoethyl 18-O-(tetrahydro-2-pyranyl)-reserpate.

The starting material used in the above reaction may be prepared as follows: A mixture of 88 g. of a 33% aqueous N,N-dimethylmethylenediamine solution and 150 ml. of ether is cooled to 5° and a total of 108.5 of ethyl chloroformate is added in portions. A solution of 40 g. of sodium hydroxide in 60 ml. of water is given to the reaction mixture simultaneously with the second half of the ethyl chloroformate; stirring is continued for an additional hour. The ether layer is separated, the aqueous portion is extracted with ether and the ether extracts are combined and dried over anhydrous potassium carbonate. The ether is evaporated, the residue is distilled, B.P. 118-122° at 17-20 mm., to yield the ethyl N-(2-dimethylaminoethyl)-carbamate.

A solution of 40 g. of ethyl N-(2-dimethylaminoethyl)-carbamate in 125 ml. of methylene chloride is cooled to 0°, and 19.5 g. of nitrosyl chloride in 300 ml. of methylene chloride is added over a period of approximately one hour while stirring and keeping the temperature between 0° to 5°. Stirring is continued for an additional two hours, the precipitate is filtered off and recrystallized from

32

ethyl acetate to yield ethyl N-(2-dimethylaminoethyl)-N-nitroso-carbamate hydrochloride, M.P. 133-135°.

A suspension of 11.3 g. of ethyl N-(2-dimethylaminoethyl)-N-nitroso-carbamate hydrochloride in 100 ml. of ether is added to a mixture of 40 g. of a 25 percent methanol solution of potassium hydroxide and 300 ml. of ether while gently refluxing. After fifteen minutes of additional heating the ether layer, containing the 2-dimethylamino-diazoethane, is decanted and immediately used.

To the above described ether solution is added portionwise 12.0 g. of reserpic acid in methylene chloride and methanol. The mixture is allowed to stand overnight at room temperature, the solvents are evaporated under reduced pressure, and the residue is added to 400 ml. of water containing 20 ml. of ammonium hydroxide. The water solution is extracted with methylene chloride, the organic solution is filtered through a column containing a diatomaceous earth and evaporated. The 2-dimethylaminoethyl reserpate is recrystallized from a mixture of ethyl acetate and petroleum ether, M.P. 110-114°.

Other deserpdates may be prepared according to the previously given procedure by replacing the starting material by other deserpdates; such compounds are, for example,

- 25 2-N,N-diethylaminoethyl 18-O-(tetrahydro-2-pyranyl)-reserpate,
 2-(1-piperidino)-ethyl 18-O-(tetrahydro-2-pyranyl)-reserpate,
 2-(4-methyl-1-piperazino)-ethyl 18-O-(tetrahydro-2-pyranyl)-reserpate,
 30 3-N,N-dimethylaminopropyl 18-O-(tetrahydro-2-pyranyl)-reserpate,
 2-N,N-dimethylaminoethyl 18-O-(tetrahydro-2-pyranyl)-deserpdate,
 35 3-N,N-diethylaminopropyl 18-O-(tetrahydro-2-pyranyl)-deserpdate,
 2-N,N-dimethylaminoethyl 5-methyl-18-O-(tetrahydro-2-pyranyl)-reserpate,
 40 2-N,N-dimethylaminoethyl 5-methyl-18-O-(tetrahydro-2-pyranyl)-deserpdate,
 2-N,N-dimethylaminoethyl 6-methyl-18-O-(tetrahydro-2-pyranyl)-reserpate,
 45 2-N,N-dimethylaminoethyl 9-methyl-18-O-(tetrahydro-2-pyranyl)-deserpdate,
 2-N,N-dimethylaminoethyl 11-methyl-18-O-(tetrahydro-2-pyranyl)-deserpdate,
 2-N,N-dimethylaminoethyl 9-methoxy-18-O-(tetrahydro-2-pyranyl)-deserpdate,
 50 2-N,N-dimethylaminoethyl 10-methoxy-18-O-(tetrahydro-2-pyranyl)-deserpdate,
 2-N,N-dimethylaminoethyl 10-methoxy-18-O-(tetrahydro-2-pyranyl)-reserpate,
 2-N,N-dimethylaminoethyl 12-methoxy-18-O-(tetrahydro-2-pyranyl)-deserpdate,
 55 2-N,N-dimethylaminoethyl 11-ethoxy-18-O-(tetrahydro-2-pyranyl)-deserpdate,
 2-N,N-dimethylaminoethyl 11-n-propyloxy-18-O-(tetrahydro-2-pyranyl)-deserpdate,
 60 2-N,N-diethylaminoethyl 11-isopropyloxy-18-O-(tetrahydro-2-pyranyl)-deserpdate,
 2-N,N-dimethylaminoethyl 11-n-butyloxy-18-O-(tetrahydro-2-pyranyl)-deserpdate,
 2-N,N-dimethylaminoethyl 10,11-methylenedioxy-18-O-(tetrahydro-2-pyranyl)-deserpdate,
 65 2-N,N-dimethylaminoethyl 10-benzyloxy-18-O-(tetrahydro-2-pyranyl)-deserpdate,
 2-N,N-dimethylaminoethyl 11-benzyloxy-18-O-(tetrahydro-2-pyranyl)-deserpdate,
 70 2-N,N-dimethylaminoethyl 11-methylmercapto-18-O-(tetrahydro-2-pyranyl)-deserpdate,
 3-N,N-dimethylaminopropyl 11-ethylmercapto-18-O-(tetrahydro-2-pyranyl)-deserpdate,
 2-N,N-dimethylaminoethyl 10-chloro-18-O-(tetrahydro-2-pyranyl)-deserpdate,

2-N,N-dimethylaminoethyl 10-bromo-18-O-(tetrahydro-2-pyranyl)-deserpdate,
 2-N,N-dimethylaminoethyl 17-desmethoxy-17-ethoxy-18-O-(tetrahydro-2-pyranyl)-reserpate,
 2-N,N-dimethylaminoethyl 17-desmethoxy-17-n-propyl-oxy-18-O-(tetrahydro-2-pyranyl)-reserpate,
 2-N,N-dimethylaminoethyl 17-desmethoxy-17-isopropyl-oxy-18-O-(tetrahydro-2-pyranyl)-reserpate
 and the like.

Example 7

To 1 g. of ethyl reserpate in 25 ml. of 2,3-dihydropyran is given 25 ml. of benzene, which has been freshly saturated with hydrogen chloride. The mixture is allowed to stand at room temperature for 45 minutes. After cooling in ice-water 20 ml. of cold 10 percent aqueous sodium hydroxide containing a small amount of ammonia is added to the mixture while shaking. Two layers separate quickly; the organic portion is washed twice with ice-water containing a small amount of ammonia and then dried over sodium sulfate while cooling. The solution is filtered and evaporated under reduced pressure at less than 55°. An amber oil is recovered, petroleum ether is added and evaporated again and the resulting residue is dissolved in fresh petroleum ether. After cooling the solution overnight in the refrigerator, 1 g. of solid material is filtered off, washed with petroleum ether and dissolved in 25 ml. of methylene chloride containing two drops of aqueous ammonia. The solution is filtered through a synthetic magnesia-silica gel preparation, which is washed with an additional amount of methylene chloride, until a total of 100 ml. is collected. The solvent is evaporated under reduced pressure; the resulting foam crystallizes upon adding a small amount of diethyl ether. The ethyl 18-O-(tetrahydro-2-pyranyl)-reserpate is filtered and washed with diethyl ether, then with petroleum ether, M.P. 210-218°; yield: 0.6 g.

Example 8

A mixture of 1 g. of n-butyl reserpate (M.P. 116-118°, prepared by treating reserpic acid with an ether solution of n-diazobutane) in 25 ml. of 2,3-dihydropyran, to which is added 25 ml. of benzene, which has been freshly saturated with hydrogen chloride, is allowed to stand for 30 minutes and is then worked up as shown in Example 7. 0.08 g. of n-butyl 18-O-(tetrahydro-2-pyranyl)-reserpate, M.P. 190-192°, is obtained.

Example 9

To a solution of 2 g. of n-hexyl reserpate in 15 ml. of acetone and 2 ml. of 2,3-dihydropyran is added dropwise, at room temperature and while stirring a solution of 1.2 g. of p-toluene-sulfonic acid in 5 ml. of acetone. The mixture is allowed to stand at room temperature for thirty minutes, and is then diluted with an excess of ethyl acetate. The organic solution is washed with 10 percent aqueous ammonia to remove all traces of the acid, the ethyl acetate solution is dried, evaporated to dryness, and the oily residue is crystallized from a mixture of ether and petroleum ether. The crystalline material is filtered off and washed with a small amount of petroleum ether to yield the desired n-hexyl 18-O-(tetrahydro-2-pyranyl)-reserpate, M.P. 167-170°. An additional amount can be recovered from the filtrate; total yield: 0.70 g.

The n-hexyl reserpate, M.P. 117-118°, may be prepared by treating reserpic acid with an ether solution of n-diazohexane. The latter can be obtained by reacting n-hexylamine with ethyl chloroformate, nitrosating the resulting ethyl N-n-hexyl-carbamate with sodium nitrite in the presence of nitric acid, treating the ethyl N-n-hexyl-N-nitroso-carbamate with a 25 percent solution of potassium hydroxide in methanol in the presence of ether and separating the ether solution of n-diazohexane; these reactions are carried out as previously shown.

Example 10

To a suspension of 20.0 g. of methyl reserpate in 150 ml. of acetone containing 20 ml. of 2,3-dihydropyran is

added dropwise while vigorously stirring a solution of 12.0 g. of p-toluene-sulfonic acid in 50 ml. of acetone. The temperature is kept below 35-50° by external cooling. A clear amber solution forms during the addition of the p-toluene sulfonic acid. The reaction mixture is allowed to stand at room temperature for thirty minutes and is then diluted with 250 ml. of ethyl acetate; the mixture is repeatedly washed with 10 percent aqueous ammonia to completely remove any remaining acid. The ethyl acetate solution is washed with water, dried over anhydrous sodium sulfate and concentrated to the small volume, when crystallization occurs. The crystalline material is filtered off and washed with ether to yield the desired methyl 18-O-(tetrahydro-2-pyranyl)-reserpate, M.P. 262-264°. The product is identical in every respect with the compound obtained according to the procedure of Example 1.

Instead of hydrogen chloride or p-toluenesulfonic acid, fluoboric acid may be used as the Lewis acid in the previously described procedures.

Example 11

A mixture of 1.0 g. of methyl 5-methyl-reserpate and 2 ml. of 2,3-dihydropyran, when reacted according to the procedure of Example 10, i.e. in the presence of 0.6 g. of p-toluene sulfonic acid and 20 ml. of acetone, yields the methyl 5-methyl-18-O-(tetrahydro-2-pyranyl)-reserpate.

Example 12

Treatment of an acetone solution of 0.5 g. of methyl 6-methyl-deserpdate with 0.8 ml. of 2,3-dihydropyran in the presence of 0.4 g. of p-toluene sulfonic acid according to the procedure of Example 10, yields the methyl 6-methyl-18-O-(tetrahydro-2-pyranyl)-deserpdate.

Example 13

Methyl 6-methyl-18-O-(tetrahydro-2-pyranyl)-reserpate can be formed by reacting an acetone solution of 1.0 g. of methyl 6-methyl-reserpate with 2 ml. of 2,3-dihydropyran in the presence of 0.5 g. of p-toluene sulfonic acid according to the procedure described in Example 10.

Example 14

0.5 g. of n-propyl 6-methyl-reserpate, when treated with 1 ml. of 2,3-dihydropyran in the presence of 0.3 g. of p-toluene sulfonic acid and acetone according to the procedure of Example 10, yields the desired n-propyl 6-methyl-18-O-(tetrahydro-2-pyranyl)-reserpate.

Example 15

A mixture of 1.0 g. of methyl 9-methyl-deserpdate, 1 ml. of 2,3-dihydropyran and 0.6 g. of p-toluene sulfonic acid in acetone, when treated according to the procedure of Example 10, yields the methyl 9-methyl-18-O-(tetrahydro-2-pyranyl)-deserpdate.

Other compounds, which may be prepared according to the previously described method by selecting the appropriate starting materials are, for example, ethyl 9-methyl-18-O-(tetrahydro-2-pyranyl)-deserpdate, methyl 11-methyl-18-O-(tetrahydro-2-pyranyl)-deserpdate, n-propyl 11-methyl-18-O-(tetrahydro-2-pyranyl)-deserpdate and the like.

Example 16

By reacting 1.0 g. of methyl 10-methoxy-deserpdate with 2 ml. of 2,3-dihydropyran according to the method described in Example 10, i.e. in an acetone solution and in the presence of 0.6 g. of p-toluene sulfonic acid, the methyl 10-methoxy-18-O-(tetrahydro-2-pyranyl)-deserpdate can be prepared.

Analogous compounds, such as, for example, methyl 9-methoxy-18-O-(tetrahydro-2-pyranyl)-deserpdate, ethyl 10-methoxy-18-O-(tetrahydro-2-pyranyl)-deserpdate, n-propyl 10-methoxy-18-O-(tetrahydro-2-pyranyl)-deserpdate, methyl 10-methoxy-18-O-(tetrahydro-2-pyranyl)-reserpate, n-propyl 10-methoxy-18-O-(tetrahydro-2-pyranyl)-reserpate and the like, may be prepared accordingly by using appropriate starting materials.

Example 17

The methyl 12-methoxy-18-O-(tetrahydro-2-pyranyl)-deserpide may be prepared by reacting an acetone solution of 0.5 g. of methyl 12-methoxy-deserpide with 1 ml. of 2,3-dihydropyran in the presence of 0.3 g. of p-toluene sulfonic acid according to the procedure of Example 10.

Ethyl 12-methoxy-18-O-(tetrahydro-2-pyranyl)-deserpide, n-propyl 12-methoxy-18-O-(tetrahydro-2-pyranyl)-deserpide and the like may be prepared according to the previously described procedure by treating the appropriate starting materials with 2,3-dihydropyran in the presence of an acidic condensing catalyst, for example, p-toluene sulfonic acid as described in Example 10.

Example 18

A mixture of 1.0 g. of methyl 11-ethoxy-deserpide, 2 ml. of 2,3-dihydropyran and 0.6 g. of p-toluene sulfonic acid in acetone, when reacted as described in Example 10, yields the desired methyl 11-ethoxy-18-O-(tetrahydro-2-pyranyl)-deserpide.

Other compounds, which may be prepared according to the procedure of the above example by selecting the appropriate starting materials are, for example, ethyl 11-ethoxy-18-O-(tetrahydro-2-pyranyl)-deserpide, n-propyl 11-ethoxy-18-O-(tetrahydro-2-pyranyl)-deserpide, methyl 11-n-propyloxy-18-O-(tetrahydro-2-pyranyl)-deserpide, methyl 11-isopropyloxy-18-O-(tetrahydro-2-pyranyl)-deserpide, methyl 11-n-butyloxy-18-O-(tetrahydro-2-pyranyl)-deserpide and the like.

Example 19

Methyl 10,11-methylenedioxy-18-O-(tetrahydro-2-pyranyl)-deserpide may be prepared by reacting 0.5 g. of methyl 10,11-methylenedioxy-deserpide with 0.8 ml. of 2,3-dihydropyran in the presence of 0.3 g. of p-toluene sulfonic acid according to the procedure of Example 10.

The ethyl 10,11-methylenedioxy-18-O-(tetrahydro-2-pyranyl)-deserpide, n-propyl 10,11-methylenedioxy-18-O-(tetrahydro-2-pyranyl)-deserpide and the like may be prepared by substituting in the previous example ethyl 10,11-methylenedioxy-deserpide, n-propyl 10,11-methylenedioxy-deserpide and the like for the methyl 10,11-methylenedioxy-deserpide and reacting the former with 2,3-dihydropyran according to the procedure described in Example 10.

Example 20

Upon treatment of methyl 1.0 g. of 10-benzyloxy-deserpide with 1.5 ml. of 2,3-dihydropyran in the presence of 0.6 g. of p-toluene sulfonic acid according to the procedure of Example 10, the methyl 10-benzyloxy-18-O-(tetrahydro-2-pyranyl)-deserpide can be obtained.

The ethyl 10-benzyloxy-18-O-(tetrahydro-2-pyranyl)-deserpide, methyl 11-benzyloxy-18-O-(tetrahydro-2-pyranyl)-deserpide and the like may be prepared by reacting the appropriate starting materials with 2,3-dihydropyran according to the procedure of Example 10.

Example 21

0.5 g. of methyl 11-methylmercapto-deserpide, when treated with 0.9 ml. of 2,3-dihydropyran in the presence of 0.3 g. of p-toluene sulfonic acid according to the procedure of Example 10, yields methyl 11-methylmercapto-18-O-(tetrahydro-2-pyranyl)-deserpide.

Ethyl 11-methylmercapto-deserpide or methyl 11-ethylmercapto-deserpide, when reacted with 2,3-dihydropyran according to the procedure of Example 10, yield the ethyl 11-methylmercapto-18-O-(tetrahydro-2-pyranyl)-deserpide and the methyl 11-ethylmercapto-18-O-(tetrahydro-2-pyranyl)-deserpide, respectively.

Example 22

The reaction of 0.6 g. of methyl 10-chloro-deserpide with 1 ml. of 2,3-dihydropyran in the presence of 0.4

g. of p-toluene sulfonic acid and in an acetone solution according to the procedure described in Example 10, yields the desired methyl 10-chloro-18-O-(tetrahydro-2-pyranyl)-deserpide.

Analogous compounds, which may be prepared according to the procedure of Example 10 by selecting the appropriate starting materials, are, for example, ethyl 10-chloro-18-O-(tetrahydro-2-pyranyl)-deserpide, n-propyl 10-chloro-18-O-(tetrahydro-2-pyranyl)-deserpide, methyl 10-fluoro-18-O-(tetrahydro-2-pyranyl)-deserpide, methyl 11-chloro-18-O-(tetrahydro-2-pyranyl)-deserpide, methyl 10-bromo-18-O-(tetrahydro-2-pyranyl)-reserpate, methyl 10-bromo-18-O-(tetrahydro-2-pyranyl)-deserpide and the like.

Example 23

Methyl 17-desmethoxy-17-ethoxy-reserpate (0.5 g.), when reacted with 1 ml. of 2,3-dihydropyran in the presence of 0.3 g. of p-toluene sulfonic acid according to the procedure of Example 10, yields the methyl 17-desmethoxy-17-ethoxy-18-O-(tetrahydro-2-pyranyl)-reserpate.

Other compounds which may be prepared according to the procedure of Example 10 by selecting the appropriate starting materials, are, for example, ethyl 17-desmethoxy-17-ethoxy-18-O-(tetrahydro-2-pyranyl)-reserpate, methyl 17-desmethoxy-17-n-propyloxy-18-O-(tetrahydro-2-pyranyl)-reserpate, methyl 17-desmethoxy-17-isopropyloxy-18-O-(tetrahydro-2-pyranyl)-reserpate, methyl 17-desmethoxy-17-ethoxy-18-O-(tetrahydro-2-pyranyl)-deserpide and the like.

Example 24

To 2.0 g. of methyl reserpate and 2 ml. of 2,3-dihydrofuran in 15 ml. of acetone is added slowly a solution of 1.2 g. of p-toluene sulfonic acid in 5 ml. of acetone at room temperature while stirring. After the addition is completed, the solution is allowed to stand at room temperature for 25 minutes, 100 ml. of ethyl acetate is added, the solution is washed with 10 percent aqueous ammonia, then with water and dried over sodium sulfate. The solution is concentrated under reduced pressure until crystals appear. The crystalline material is filtered off and washed with ether to yield 0.7 g. of methyl 18-O-(tetrahydro-2-furanyl)-reserpate, M.P. 256-258° (decomposition).

Other lower alkyl 18-O-(tetrahydro-2-furanyl)-deserpide compounds, which may be prepared according to the above-described procedure by selecting the appropriate starting materials are, for example, ethyl 18-O-(tetrahydro-2-furanyl)-reserpate, n-propyl 18-O-(tetrahydro-2-furanyl)-reserpate, isopropyl 18-O-(tetrahydro-2-furanyl)-reserpate, n-butyl 18-O-(tetrahydro-2-furanyl)-reserpate, isobutyl 18-O-(tetrahydro-2-furanyl)-reserpate, methyl 18-O-(tetrahydro-2-furanyl)-deserpide, ethyl 18-O-(tetrahydro-2-furanyl)-deserpide, methyl 6-methyl-18-O-(tetrahydro-2-furanyl)-reserpate, methyl 9-methyl-18-O-(tetrahydro-2-furanyl)-deserpide, methyl 10-methoxy-18-O-(tetrahydro-2-furanyl)-deserpide, methyl 11-ethoxy-18-O-(tetrahydro-2-furanyl)-deserpide, methyl 12-methoxy-18-O-(tetrahydro-2-furanyl)-deserpide, methyl 10-bromo-18-O-(tetrahydro-2-furanyl)-deserpide, methyl 10-methylmercapto-18-O-(tetrahydro-2-furanyl)-deserpide, methyl 17-desmethoxy-17-ethoxy-18-O-(tetrahydro-2-furanyl)-reserpate and the like.

70

75

Example 25

A mixture of 2.0 g. of methyl reserpate and 2 ml. of 4-methyl-2,3-dihydropyran in 15 ml. of acetone is stirred, while a solution of 1.2 g. of p-toluene sulfonic acid in 5 ml. of acetone is added slowly. The reaction mixture is allowed to stand at room temperature for 1½ hours, 100 ml. of ethyl acetate is added and the diluted mixture is washed with 10 percent aqueous ammonia and then with water. The organic layer is dried over sodium sulfate and concentrated to dryness under reduced pres-

sure; the oily residue crystallizes when stirred with diethyl ether. The solid material is recrystallized from ethanol to yield the desired methyl 18-O-(4-methyl-tetrahydro-2-pyranyl)-reserpate, M.P. 250-252° (with decomposition).

Analogous deserpidate compounds, such as, for example, ethyl 18-O-(4-methyl-tetrahydro-2-pyranyl)-reserpate, n-propyl 18-O-(4-methyl-tetrahydro-2-pyranyl)-reserpate, methyl 18-O-(4-methyl-tetrahydro-2-pyranyl)-deserpidate, methyl 10-methoxy-18-O-(4-methyl-tetrahydro-2-pyranyl)-deserpidate, methyl 12-methoxy-18-O-(4-methyl-tetrahydro-2-pyranyl)-deserpidate and the like, may be prepared by reacting the appropriate starting materials with 4-methyl-2,3-dihydropyran as shown in the above example.

Example 26

To a solution of 2.0 g. of isopropyl reserpate and 5 ml. of 2,3-dihydropyran in 15 ml. of acetone is added dropwise and at room temperature while stirring a solution of 1.2 g. of p-toluene sulfonic acid in 5 ml. of acetone. The solution warms up towards the end of the addition of the acid and darkens in color; it is stirred for an additional thirty minutes. To the reaction mixture is added an excess of ethyl acetate, the solution is washed with 10 percent aqueous sodium hydroxide and water and then dried over anhydrous sodium sulfate. The solvent is evaporated to yield an oil, which crystallizes upon adding diethyl ether to yield the desired isopropyl 18-O-(tetrahydro-2-pyranyl)-reserpate, M.P. 250-253°; yield: 0.475 g.

The starting material used in the above reaction may be prepared as follows: A mixture of 10 g. of methyl reserpate, 500 ml. of isopropanol and 20 drops of benzyl trimethyl ammonium hydroxide is refluxed for 2½ hours. After standing at room temperature for several hours, a white precipitate (needles) is formed, which is removed by filtration. The filtrate is evaporated to dryness, the foamy residue is taken up in 500 ml. of water containing 5 ml. of concentrated aqueous ammonia. The aqueous mixture is extracted with methylene chloride, the organic solvent is passed through a column containing a diatomaceous earth preparation and is then evaporated to dryness under reduced pressure. The residue is crystallized by the addition of diethyl ether, the crystalline material is filtered off, dried and identified as isopropyl reserpate, M.P. 214-216°.

Example 27

A solution of 1.2 g. of p-toluene sulfonic acid in 5 ml. of acetone is added dropwise to 2 g. of isobutyl reserpate and 2 ml. of 2,3-dihydropyran in 15 ml. of acetone. The reaction mixture is stirred and kept at room temperature during the addition and is then allowed to stand at the same temperature for an additional thirty minutes. An excess of ethyl acetate is added, the organic portion is washed with 10 percent aqueous ammonia to neutralize the acid and is then dried and evaporated to dryness. The residue is crystallized from a mixture of ether and petroleum ether to yield the desired isobutyl 18-O-(tetrahydro-2-pyranyl)-reserpate, which, after washing with a small amount of petroleum ether, melts at 206-208°; yield: 0.75 g.

The isobutyl reserpate may be prepared as follows: To a stirred solution of 34 g. of ethyl N-isobutyl-carbamate in 120 ml. of methylene chloride, kept at 0°, is added dropwise 15 g. of nitrosyl chloride, whereby the temperature is not allowed to raise to more than 5°. The mixture is stirred for an additional hour, the solvent is evaporated under reduced pressure and the resulting ethyl N-isobutyl-N-nitroso-carbamate is used in the following step without any further purification.

A mixture of 30 g. of ethyl N-isobutyl-N-nitroso-carbamate and 75 ml. of ether is added dropwise to a refluxing mixture of 50 g. of a 25 percent solution of

potassium hydroxide in methanol, and 300 ml. of ether. The mixture is refluxed for an additional thirty minutes, an excess of water is added and the organic phase is separated, washed with water and dried over anhydrous sodium sulfate. The ether solution of the resulting diazoisobutane is used in the next step.

A total of 6 g. of reserpic acid is added in small amounts to the ether solution of diazoisobutane over a period of four hours. The ether is then evaporated under reduced pressure, the residue is added to a solution of 20 ml. of concentrated aqueous ammonia in 600 ml. of water. The aqueous solution is extracted with methylene chloride, the organic layer is separated, passed through a short column containing a synthetic magnesium silicate adsorbent preparation and then evaporated. The residue is distilled under reduced pressure to remove unreacted ethyl N-isobutyl-carbamate (B.P. 93-94°/15 mm.), and the non-distillable material is recrystallized from ether to yield isobutyl reserpate, M.P. 145-148°; yield: 3.0 g.

Example 28

To a mixture of 2.0 g. of isopentyl reserpate and 2 ml. of 2,3-dihydropyran in 25 ml. of acetone is added gradually 1.2 g. of p-toluene sulfonic acid in 5 ml. of acetone. After standing at room temperature for thirty minutes an excess of ethyl acetate is added; the resulting mixture is then washed twice with 10 percent aqueous sodium hydroxide. The organic layer is dried over sodium sulfate and evaporated under reduced pressure; the oily residue is heated in a distillation apparatus to about 120° under reduced pressure. Ethyl acetate is added to the non-distillable residue, a crystalline material precipitates, which is filtered off and dissolved in methylene chloride. The solution is passed through a column containing a synthetic magnesium silicate adsorbent preparation; the residue obtained after evaporating the solvent from the eluate is crystallized from ethyl acetate to yield isopentyl 18-O-(tetrahydro-2-pyranyl)-reserpate, M.P. 130-135°; yield: 0.12 g.

The starting material may be prepared as follows: To a solution of 60 g. of ethyl N-isopentyl-carbamate, B.P. 107-108°/17-20 mm. (prepared by reacting isopentylamine with ethyl chloroformate in the presence of sodium hydroxide and in a mixture of water and ether) in 150 ml. of ether is added 50 g. of ice and then 163 g. of sodium nitrite in 250 ml. of water. A solution of 150 g. of concentrated nitric acid and 150 g. of ice is gradually given to the reaction mixture over a period of 1½ hours, keeping the temperature below 15° by adding more ice. The separated ether layer is washed twice with water and cold aqueous potassium carbonate, and is then dried over potassium carbonate. The solvent is removed on the steam bath, leaving ethyl N-isopentyl-N-nitroso-carbamate, yield: 78 g.

A mixture of 40.0 g. of ethyl N-isopentyl-N-nitroso-carbamate in 75 ml. of ether is added dropwise to 80.0 g. of a 25 percent solution of potassium hydroxide in methanol and 400 ml. of ether while refluxing. Boiling is continued for an additional twenty minutes. An excess of water is added, the ether layer is separated, washed with water and dried over sodium sulfate.

To the ether solution, containing the diazoisopentane, is added reserpic acid hydrochloride portionwise until no further liberation of gas is observed. The reaction mixture is stirred overnight at room temperature, the ether is removed under reduced pressure, the residue is dissolved in methylene chloride, the organic phase is washed with water containing ammonium hydroxide and then passed through a short column containing a synthetic magnesium silicate adsorbent preparation. The residue, obtained after evaporating the solvent of the eluate, crystallizes from a mixture of ethyl acetate and petroleum ether after an initially precipitating gum has been removed. The crystalline isopentyl reserpate melts at 135-138°; yield: 4.13 g.

Example 29

1.0 g. of 18-O-(tetrahydro-2-pyranyl)-reserpic acid is added in small amounts to an ether solution of diazoethane until evolution of nitrogen ceases. The reaction mixture is allowed to stand at room temperature, an excess of benzoic acid in ether is added and the solvent is evaporated. Dilute aqueous ammonia is given to the residue, and the aqueous mixture is extracted with methylene chloride. The organic solvent is evaporated after drying and the residue is worked up to yield the desired ethyl 18-O-(tetrahydro-2-pyranyl)-reserpate, M.P. 210-218°.

The starting material may be prepared as follows: A solution of 3.6 g. of methyl 18-O-(tetrahydro-2-pyranyl)-reserpate in 45 ml. of 1 N aqueous sodium hydroxide is refluxed for 2½ hours. The resulting solution is concentrated under reduced pressure, and the residue is diluted with water. The solution is adjusted to pH=7 with acetic acid and then extracted with methylene chloride. The organic solution is dried over sodium sulfate, the solvent is evaporated under reduced pressure and the residue is crystallized from a mixture of ethyl acetate and ethylene chloride to yield 1.5 g. of 18-O-(tetrahydro-2-pyranyl)-reserpic acid, M.P. 215-218° (with decomposition).

The 18-O-(tetrahydro-2-pyranyl)-reserpic acid may also be prepared as follows: To 0.5 g. of reserpic acid hydrochloride in 10 ml. of N,N-dimethylformamide and 5 ml. of 2,3-dihydropyran is added dropwise 0.3 g. of p-toluene sulfonic acid in 5 ml. of N,N-dimethylformamide while stirring at room temperature. The solution is stirred for an additional thirty minutes, and is then poured into water; the mixture is extracted with methylene chloride, the organic layer is dried over anhydrous sodium sulfate and evaporated under reduced pressure. The residue is crystallized by adding diethyl ether and stirring until crystals appear. The solid material is filtered off, washed with ether, dried and recrystallized from a mixture of ethyl acetate and methylene chloride, M.P. 200-205°; yield: 0.3 g.

Other 18-O-(tetrahydro-2-pyranyl)-deserpodic acid compounds, such as for example, 18-O-(tetrahydro-2-pyranyl)-deserpodic acid, 5-methyl-18-O-(tetrahydro-2-pyranyl)-reserpic acid, 5-methyl-18-O-(tetrahydro-2-pyranyl)-deserpodic acid, 6-methyl-18-O-(tetrahydro-2-pyranyl)-reserpic acid, 9-methyl-18-O-(tetrahydro-2-pyranyl)-deserpodic acid, 11-methyl-18-O-(tetrahydro-2-pyranyl)-deserpodic acid, 9-methoxy-18-O-(tetrahydro-2-pyranyl)-deserpodic acid, 10-methoxy-18-O-(tetrahydro-2-pyranyl)-deserpodic acid, 10-methoxy-18-O-(tetrahydro-2-pyranyl)-reserpic acid, 12-methoxy-(tetrahydro-2-pyranyl)-deserpodic acid, 11-ethoxy-18-O-(tetrahydro-2-pyranyl)-deserpodic acid, 11-n-propoxy-18-O-(tetrahydro-2-pyranyl)-deserpodic acid, 11-isopropoxy-18-O-(tetrahydro-2-pyranyl)-deserpodic acid, 11-n-butyloxy-18-O-(tetrahydro-2-pyranyl)-deserpodic acid, 10,11-methylenedioxy-18-O-(tetrahydro-2-pyranyl)-deserpodic acid, 10-benzylxy-18-O-(tetrahydro-2-pyranyl)-deserpodic acid, 11-benzylxy-18-O-(tetrahydro-2-pyranyl)-deserpodic acid, 11-methylmercapto-18-O-(tetrahydro-2-pyranyl)-deserpodic acid, 11-ethylmercapto-18-O-(tetrahydro-2-pyranyl)-deserpodic acid, 10-chloro-18-O-(tetrahydro-2-pyranyl)-deserpodic acid, 10-bromo-18-O-(tetrahydro-2-pyranyl)-deserpodic acid, 17-desmethoxy-17-ethoxy-18-O-(tetrahydro-2-pyranyl)-reserpic acid, 17-desmethoxy-17-n-propoxy-18-O-(tetrahydro-2-pyranyl)-reserpic acid, 17-desmethoxy-17-isopropoxy-18-O-(tetrahydro-2-pyranyl)-reserpic acid and the like, may either be prepared by hydrolysis, for example, of the corresponding lower alkyl 18-O-(tetrahydro-2-pyranyl)-deserpodic compounds, or by treatment of the corresponding deserpodic acid compounds with 2,3-dihydropyran as shown hereinabove.

2,3-dihydropyran may be replaced by a 2-halogeno-tetrahydropyran, such as 2-chloro-tetrahydropyran, which upon reaction with a deserpodic acid compound, e.g. reserpic, deserpodic acid and the like, in the presence of

N,N-dimethylformamide as shown in Example 33, yields the desired 18-O-(tetrahydro-2-pyranyl)-deserpodic acid compound, e.g. 18-O-(tetrahydro-2-pyranyl)-reserpic acid, 18-O-(tetrahydro-2-pyranyl)-deserpodic acid and the like can be formed.

18-O-(tetrahydro-2-furanyl)-deserpodic acid compounds, such as for example, 18-O-(tetrahydro-2-furanyl)-reserpic acid, 18-O-(tetrahydro-2-furanyl)-deserpodic acid, 10-methoxy-18-O-(tetrahydro-2-furanyl)-deserpodic acid, 12-methoxy-18-O-(tetrahydro-2-furanyl)-deserpodic acid and the like, can be obtained by hydrolyzing a corresponding lower alkyl 18-O-(tetrahydro-2-furanyl)-deserpodic compound or by reacting a mixture of the corresponding 18-unsubstituted deserpodic acid compound and 2,3-dihydrofuran in an N,N-dimethylformamide solution with p-toluene sulfonic acid as shown in the above example.

Example 30

A solution of 0.5 g. of methyl 18-O-(tetrahydro-2-pyranyl)-reserpate, prepared, for example, according to the procedure of Example 10, in ethanol containing sodium ethanolate, when heated to reflux over a short period of time, yields the desired ethyl 18-O-(tetrahydro-2-pyranyl)-reserpate, M.P. 210-218°.

Example 31

To a solution of 1.29 g. of methyl reserpate N-oxide and 1.25 ml. of 2,3-dihydropyran in 10 ml. of acetone is gradually added, while stirring, 0.76 g. of p-toluene sulfonic acid in 3.2 ml. of acetone. Stirring is continued for an additional thirty minutes and ethyl acetate is added; the organic layer is washed twice with 10 percent aqueous sodium hydroxide and with water. The organic solution is dried over sodium sulfate, the solvent is removed under reduced pressure, and the residue is precipitated from a mixture of acetone and diethyl ether and crystallized from ethyl acetate. The resulting methyl 18-O-(tetrahydro-2-pyranyl)-reserpate N-oxide melts at 226-227°; yield: 0.11 g.

Other N-oxides, such as, for example, ethyl 18-O-(tetrahydro-2-pyranyl)-reserpate N-oxide, n-propyl 18-O-(tetrahydro-2-pyranyl)-reserpate N-oxide, methyl 18-O-(tetrahydro-2-pyranyl)-deserpodic N-oxide, methyl 10-methoxy-18-O-(tetrahydro-2-pyranyl)-deserpodic N-oxide, methoxyethyl 18-O-(tetrahydro-2-pyranyl)-reserpate N-oxide, methyl 18-O-(4-methyl-tetrahydro-2-pyranyl)-reserpate N-oxide, methyl 18-O-(tetrahydro-2-furanyl)-reserpate N-oxide and the like, may be obtained by reacting the appropriate lower alkyl or lower alkoxy-lower alkyl deserpodic N-oxide compounds with 2,3-dihydropyran, 4-methyl-2,3-dihydropyran, 2,3-dihydrofuran and the like according to the above procedure.

Example 32

A suspension of 249.3 g. of methyl reserpate in 1870 ml. of acetone and 250 ml. of 2,3-dihydropyran is stirred at room temperature; a solution of 129.3 g. of p-toluene sulfonic acid monohydrate in 620 ml. of acetone is added over a period of nine minutes. The resulting solution is stirred for thirty minutes, the acetone is removed by distillation and the residue is suspended in 2500 ml. of ethyl acetate. The organic solution is washed with a mixture of 602 ml. of 10 percent aqueous sodium carbonate and 780 ml. of water, and then three times with 300 ml. of water. 1000 ml. of chloroform is added, the remaining water is distilled azeotropically and the solution is cooled. A precipitate is formed, is filtered off and washed with ethyl acetate and then with ether. The isolated product is identical in every respect with the methyl 18-O-(tetrahydro-2-pyranyl)-reserpate obtained according to the procedure of Example 10; its rotation is $[\alpha]_D^{26} = -148.75^\circ$ (in chloroform); yield: 107.6 g.

The filtrate, obtained after separating the solid material, is concentrated to 400 ml. and the oily residue is dissolved in 500 ml. of isopropanol. On cooling at 5° overnight, a precipitate is formed, which is filtered off, washed

with isopropanol and dried. This product represents a methyl 18-O-(tetrahydro-2-pyranyl)-reserpate, which is isomeric with the product described hereinbefore and differs from the material previously obtained according to the procedure of Examples 1, 2 and 10. It melts at 219-221° and its rotation is $[\alpha]_D^{26} = -39.93^\circ$ (in chloroform).

Example 33

A solution of 3.0 g. of 2-chloro-tetrahydropyran and 3.0 g. of methyl reserpate in 27 ml. of freshly distilled N,N-dimethylformamide is allowed to stand at room temperature in the dark for nine days. The solution is then poured into 500 ml. of cold water, the resulting solution is made alkaline by adding 15 ml. of concentrated aqueous ammonia. The resulting white precipitate is filtered off, washed with water and then dried. It is dissolved in hot ethyl acetate, the solution is concentrated until crystals separate. A total of 0.39 g. of pure methyl 18-O-(tetrahydro-2-pyranyl)-reserpate, M.P. 253-255° is obtained, which is identical in every respect with the compound obtained according to the procedure of Example 10.

Other lower alkyl, lower alkoxy or N,N-di-lower alkyl-amino-lower alkyl 18-O-(tetrahydro-2-pyranyl)-deserpide compounds, such as, for example, ethyl 18-O-(tetrahydro-2-pyranyl)-reserpate, n-propyl 18-O-(tetrahydro-2-pyranyl)-reserpate, methyl 18-O-(tetrahydro-2-pyranyl)-deserpide, methyl 10-methoxy-18-O-(tetrahydro-2-pyranyl)-deserpide, 2-methoxyethyl 18-O-(tetrahydro-2-pyranyl)-reserpate, 2-N,N-dimethylaminoethyl 18-O-(tetrahydro-2-pyranyl)-reserpate, and the like may be obtained by reacting the corresponding lower alkyl, lower alkoxy-lower alkyl or N,N-di-lower alkyl-amino-lower alkyl deserpide compounds with a 2-halogeno-tetrahydropyran, particularly 2-chloro-tetrahydropyran, as shown in the above procedure.

2-halogeno-tetrahydropyrans may be replaced, for example, by 2-halogeno-tetrahydrofurans, e.g. 2-chloro-tetrahydrofuran, which, upon treatment with lower alkyl deserpide compounds, e.g. methyl deserpide, methyl reserpate and the like, in the presence of N,N-dimethylformamide yield lower alkyl 18-O-(tetrahydro-2-furanyl)-deserpide compounds, such as methyl 18-O-(tetrahydro-2-furanyl)-deserpide, methyl 18-O-(tetrahydro-2-furanyl)-reserpate and the like.

Example 34

To a solution of 3 g. of dry methyl reserpate in 27 ml. of freshly distilled N,N-dimethylformamide is added 3 ml. of 2,3-dichloro-tetrahydropyran; the reaction mixture is allowed to stand at room temperature for nine days. The dark solution is poured into 480 ml. of cold water, 15 ml. of concentrated aqueous ammonia is added, whereupon a small amount of a gummy precipitate is formed, which is filtered off. Upon stirring with methanol, the gummy material crystallizes and is recrystallized from methanol to yield the pure methyl 18-O-(3-chloro-tetrahydro-2-pyranyl)-reserpate, M.P. 258-261° (with decomposition).

Treatment of other deserpide, particularly lower alkyl deserpide, compounds, e.g. ethyl reserpate, n-propyl reserpate, methyl deserpide, methyl 10-methoxy-deserpide and the like, with 2,3-dichloro-tetrahydropyran in the presence of N,N-dimethylformamide as described hereinabove, yields the desired 18-O-(3-chloro-tetrahydro-2-pyranyl)-deserpide, particularly lower alkyl-18-O-(3-chloro-tetrahydro-2-pyranyl)-deserpide, compounds, e.g. ethyl 18-O-(3-chloro-tetrahydro-2-pyranyl)-reserpate, n-propyl 18-O-(3-chloro-tetrahydro-2-pyranyl)-reserpate, methyl 18-O-(3-chloro-tetrahydro-2-pyranyl)-deserpide, methyl 10-methoxy-18-O-(3-chloro-tetrahydro-2-pyranyl)-deserpide and the like can be obtained.

Example 35

To a solution of 0.115 g. of 85 percent aqueous phosphoric acid in 6 ml. of methanol is added 0.5 g. of methyl 18-O-(tetrahydro-2-pyranyl)-reserpate. The solution is

decanted from the insoluble material, ether is added to the separated solution, and the resulting precipitate is filtered off. It is washed with ether, dried under reduced pressure to yield 0.46 g. of a yellow powder, which contains the desired methyl 18-O-(tetrahydro-2-pyranyl)-reserpate phosphate.

Example 36

A solution of 1.0 g. of methyl 18-O-(tetrahydro-2-pyranyl)-3-iso-reserpate is heated in 35 ml. of glacial acetic acid containing a small amount of p-toluene sulfonic acid for about twenty-four hours under an atmosphere of nitrogen. Most of the solvent is removed under reduced pressure, water is added to the residue and the solution is extracted with chloroform. The organic layer is separated, washed with water and evaporated under reduced pressure. From the residue, the desired methyl 18-O-(tetrahydro-2-pyranyl)-reserpate, which is identified by paper chromatography, can be isolated by chromatography on alumina; the resulting product is identical with the compound obtained according to the procedure of Example 1.

The starting material used in the above procedure may be prepared by treating methyl 18-O-(tetrahydro-2-pyranyl)-3-iso-reserpate in acetone with 2,3-dihydropyran in the presence of a small amount of p-toluene sulfonic acid according to the procedure of Example 10.

Other lower alkyl 18-O-(2-cyclo-oxa-alkyl)-3-iso-deserpide compounds, in which cyclo-oxa-alkyl contains from five to seven atoms as ring members, such as, for example, methyl 18-O-(tetrahydro-2-furanyl)-3-iso-reserpate, ethyl 18-O-(tetrahydro-2-furanyl)-3-iso-reserpate, ethyl 18-O-(tetrahydro-2-pyranyl)-3-iso-reserpate, n-propyl 18-O-(tetrahydro-2-pyranyl)-3-iso-reserpate, methyl 18-O-(tetrahydro-2-pyranyl)-3-iso-deserpide and the like, may be prepared by treating the corresponding lower alkyl 3-iso-deserpide compounds with a cyclo-oxa-alk-2-ene, particularly 2,3-dihydrofuran, 2,3-dihydropyran and the like, in the presence of an acid condensing reagent, e.g. p-toluene sulfonic acid and the like. Upon isomerization of the above-mentioned lower alkyl 18-O-(2-cyclo-oxa-alkyl)-3-iso-deserpide compounds, for example, in a mixture of glacial acetic and p-toluene sulfonic acid, the desired compounds of the present invention can be obtained.

Example 37

To a solution of 1.0 g. of benzyl reserpate in 15 ml. of acetone, is added 1.0 g. of 2,3-dihydropyran and 0.6 g. of p-toluene sulfonic acid; the reaction mixture is allowed to stand and is then worked up as shown in Example 10 to yield the desired benzyl 18-O-(tetrahydro-2-pyranyl)-reserpate.

Upon treatment of a solution of benzyl 18-O-(tetrahydro-2-pyranyl)-reserpate in methanol with hydrogen in the presence of a catalytic amount of palladium on charcoal, the desired 18-O-(tetrahydro-2-pyranyl)-reserpic acid is formed, which can be converted into ethyl 18-O-(tetrahydro-2-pyranyl)-reserpate according to the procedure of Example 29.

Example 38

To a solution of 6.3 g. of methyl reserpate and 6.3 g. of 2-methyl-2,3-dihydropyran in 40 ml. of acetone is added slowly a solution of 3.8 g. of p-toluene sulfonic acid in 15 ml. of acetone. The temperature rises slightly; the reaction mixture is allowed to stand at room temperature for thirty minutes and is then evaporated to dryness. The gummy residue is suspended in 75 ml. of ethyl acetate and 18 ml. of a 10 percent aqueous solution of sodium carbonate and 24 ml. of water are added. The organic layer is separated, washed three times with water and diluted with 30 ml. of chloroform. The solvents are evaporated to remove traces of water by azeotropic distillation, petroleum ether is added to the gummy residue and the mixture is allowed to stand while cooling. The solvent is evaporated and the solid residue is re-

43

crystallized from isopropanol to yield the crystalline methyl 18-O-(6-methyl-tetrahydro-2-pyranyl)-reserpate, M.P. 243-245°; yield: 0.58 g.

Example 39

To a solution of 5.23 g. of methyl 18-O-(tetrahydro-2-pyranyl)-reserpate in 160 ml. of methylene chloride is added over a period of 20 minutes a total of 62 ml. of a 0.187 molar solution of perbenzoic acid in ethyl acetate. During the addition, the reaction mixture is kept at 0°; stirring is continued for 15 minutes at 0°. The resulting mixture is washed three times with a 5 percent aqueous solution of sodium hydroxide, then with water, and the organic phase is dried over sodium sulfate. The solvent is removed under reduced pressure and the resulting methyl 18-O-(tetrahydro-2-pyranyl)-reserpate N-oxide is recrystallized from ethyl acetate, M.P. 228-230°; yield: 1.67 g. The product is identical with the N-oxide obtained according to the method described in Example 31.

Example 40

A solution of 5.14 g. of 1,4-diox-2-ene in 10 ml. of dry toluene is treated with 2.18 g. of dry hydrogen chloride at from about 0° to about 10°. The resulting solution of 2-chloro-1,4-dioxane is added to 3.0 g. of dried methyl reserpate in 27 ml. of freshly distilled N,N-dimethylformamide. The reaction mixture is allowed to stand at room temperature for ten days and is then poured into 480 ml. of water, containing 15 ml. of concentrated aqueous ammonia. The resulting precipitate is filtered off and removed. The filtrate is allowed to stand for several hours at room temperature. The crystalline precipitate is filtered off and recrystallized three times from ethanol. The resulting methyl 18-O-[2-(1,4-dioxanyl)]-reserpate melts at 242-244°; yield: 0.35 g.

Ethyl reserpate, n-propyl reserpate, methyl deserpipate, methyl reserpate N-oxide and the like, when reacted with 2-chloro-1,4-dioxane in the presence of N,N-dimethylformamide according to the above-given method, yield the desired ethyl 18-O-[2-(1,4-dioxanyl)]-reserpate, n-propyl 18-O-[2-(1,4-dioxanyl)]-reserpate, methyl 18-O-[2-(1,4-dioxanyl)]-deserpipate, methyl 18-O-[2-(1,4-dioxanyl)]-reserpate N-oxide and the like. Other 18-O-[2-(1,4-dioxanyl)]-deserpipate compounds, which may be prepared according to the above procedure by selecting the appropriate starting material, are, for example, 2-methoxyethyl 18-O-[2-(1,4-dioxanyl)]-reserpate, 3-ethoxypropyl 18-O-[2-(1,4-dioxanyl)]-reserpate, 2-N,N-dimethylaminoethyl 18-O-[2-(1,4-dioxanyl)]-reserpate, 2-N,N-diethylaminoethyl 18-O-[2-(1,4-dioxanyl)]-reserpate, methyl 18-O-[2-(1,4-dioxanyl)]-5-methyl-reserpate, methyl 18-O-[2-(1,4-dioxanyl)]-5-methyl-deserpipate, methyl 18-O-[2-(1,4-dioxanyl)]-6-methyl-reserpate, methyl 18-O-[2-(1,4-dioxanyl)]-6-methyl-deserpipate, methyl 18-O-[2-(1,4-dioxanyl)]-9-methyl-deserpipate, methyl 18-O-[2-(1,4-dioxanyl)]-10-methoxy-reserpate, methyl 18-O-[2-(1,4-dioxanyl)]-10-methoxy-deserpipate, methyl 18-O-[2-(1,4-dioxanyl)]-11-ethoxy-deserpipate, methyl 18-O-[2-(1,4-dioxanyl)]-12-methoxy-deserpipate, methyl 18-O-[2-(1,4-dioxanyl)]-11-methylmercapto-deserpipate, methyl 10-chloro-18-O-[2-(1,4-dioxanyl)]-deserpipate, methyl 10-bromo-18-O-[2-(1,4-dioxanyl)]-deserpipate, methyl 10-bromo-18-O-[2-(1,4-dioxanyl)]-reserpate, methyl 17-desmethoxy-18-O-[2-(1,4-dioxanyl)]-17-ethoxy-reserpate and the like.

In the above procedure, 2-chloro-1,4-dioxane may be replaced by other reactive esters of hydroxy-cyclo-dioxa-alkanes, such as, for example, 4-chloro-1,3-dioxalane, 4-chloro-1,3-dioxane, 2-chloro-5-methyl-1,4-dioxane, 2,3-dichloro-1,4-dioxane and the like; when reacted with methyl reserpate or any other deserpipate compound in the presence of N,N-dimethylformamide according to the above procedure, these reagents yield, for example, methyl 18-O-[4-(1,3-dioxalanyl)]-reserpate, methyl 18-O-[4-

44

(1,3-dioxanyl)]-reserpate, methyl 18-O-[2-(5-methyl-1,4-dioxanyl)]-reserpate, methyl 18-O-[2-(3-chloro-1,4-dioxanyl)]-reserpate and the like, or any other 18-O-(2-cyclo-dioxa-alkyl)-deserpipate.

5

Example 41

To a solution of 3.0 g. of thoroughly dried methyl reserpate in 27 ml. of freshly distilled N,N-dimethylformamide is added 3.0 g. of freshly prepared 2-chloro-1,4-oxathiane. The reaction mixture is allowed to stand for nine days in the dark and is then poured into 500 ml. of cold water. 15 ml. of concentrated aqueous ammonia is added. The resulting precipitate is collected, washed with water and recrystallized from a minimum amount of isopropanol to yield 1.2 g. of methyl 18-O-[2-(1,4-oxathianyl)]-reserpate, M.P. 244-245°.

2-chloro-1,4-oxathiane may be reacted with other deserpipate compounds, such as, for example, ethyl reserpate, n-propyl reserpate, methyl deserpipate, methyl 5-methyl-deserpipate, methyl 6-methyl-reserpate, methyl 10-methoxy-deserpipate, methyl 12-methoxy-deserpipate, methyl 11-methylmercapto-deserpipate, methyl 10-chloro-deserpipate, methyl 10-bromo-reserpate and the like, in the presence of N,N-dimethylformamide according to the above procedure to yield, for example, ethyl 18-O-[2-(1,4-oxathianyl)]-reserpate, n-propyl 18-O-[2-(1,4-oxathianyl)]-reserpate, methyl 18-O-[2-(1,4-oxathianyl)]-deserpipate, methyl 5-methyl-18-O-[2-(1,4-oxathianyl)]-deserpipate, methyl 6-methyl-18-O-[2-(1,4-oxathianyl)]-reserpate, methyl 10-methoxy-18-O-[2-(1,4-oxathianyl)]-deserpipate, methyl 12-methoxy-18-O-[2-(1,4-oxathianyl)]-deserpipate, methyl 11-methylmercapto-18-O-[2-(1,4-oxathianyl)]-deserpipate, methyl 10-chloro-18-O-[2-(1,4-oxathianyl)]-deserpipate, methyl 10-bromo-18-O-[2-(1,4-oxathianyl)]-reserpate and the like.

In the above procedure 2-chloro-1,4-oxathiane may be replaced, for example, by 2-chloro-5-methyl-1,4-oxathiane, 2,3-dichloro-1,4-oxathiane and the like, which upon treatment with methyl reserpate or any other deserpipate compound yield methyl 18-O-[2-(5-methyl-1,4-oxathianyl)]-reserpate, 18-O-[2-(3-chloro-1,4-oxathianyl)]-reserpate or any other 18-O-(2-cyclo-oxathia-alkyl)-deserpipates.

Example 42

The deserpipate compounds of the present invention may be used in the form of pharmaceutical preparations. For example, methyl 18-O-(tetrahydro-2-pyranyl)-reserpate may be made up into therapeutically acceptable tablets containing 0.005 g. of pharmacologically reactive substance (procedure for 3000 tablets).

Ingredients:

	G.
Methyl 18-O-(tetrahydro-2-pyranyl) - reserpate	15.00
Mannitol	400.00
Talcum, U.S.P.	22.50
Magnesium stearate	2.25
Acacia	10.25
Purified water, q.s.	

The acacia is dissolved in 110.00 ml. of water, and the mannitol is granulated with the resulting solution. The granulate is dried at about 38° and passed through a 20 mesh screen. The methyl 18-O-(tetrahydro-2-pyranyl)-reserpate is mixed with the talcum and passed through a 30 mesh screen. The granulated mannitol and the magnesium stearate, which has been previously through a 20 mesh screen, are added. The ingredients are mixed well and compressed into tablets of 0.150 g. weight with $\frac{1}{32}$ inch standard concave punches.

Example 43

A composition suitable for veterinary use may be prepared as follows.

Premix:

Methyl 18-O-(tetrahydro-2-pyranyl)-reserpate	22.00
Wheat standard middlings, 30-80 mesh	10,978.00
Total weight	11,000.00

Feed formula:

Corn meal	1062.875
Fat	80.000
Fish meal, 60% protein	100.000
Soybean meal, 50% protein	500.000
Corn gluten meal	100.000
Dehydrated alfalfa meal	50.000
Corn distiller solubles	40.000
Di-calcium carbonate	28.000
Iodized salt	10.000
Vitamins A and D (1,000,000 A and 250,000 D/pound)	4.000
Calcium pantothenate	.250
Butylated hydroxy toluene	.250
Choline chloride 25%	2.500
Riboflavin conc. (24 g. per pound)	.125
Vitamin B ₁₂ (0.02 g. per pound)	1.000
Methionine	.500
Manganese sulphate	.500
Total weight	2000.000

The premix is made by adding the methyl 18-O-tetrahydro-2-pyranyl)-reserpate to the wheat and then mixing until uniformity is obtained.

The feed formula is prepared as follows: A portion of the corn meal is introduced into the blending machine (about half of the amount to be added). The remaining corn meal, previously blended with the pre-heated, liquefied fat, is added thereto and mixing is continued until uniformity is obtained. The manganese sulphate, di-calcium carbonate and iodized salt are then added with mixing, followed by the addition of the fish meal, soy bean meal, corn gluten meal and corn distiller solubles. After a uniform mixture has been obtained, vitamins A and D, calcium pantothenate, chlorine chloride, riboflavin, Vitamin B₁₂ and methionine are added in that order. Mixing is continued after the addition of butylated hydroxy toluene, and maintained until a uniform product is obtained.

The premix is added to the feed formula prepared as described above in an amount sufficient to provide a concentration of 0.18 g. of methyl 18-O-(tetrahydro-2-pyranyl)-reserpate per 1000 g. of feed in the uniformly blended mix.

For sedation and quieting of birds one may desirably use from about 0.06 to about 0.360 g. per 1000 g. of feed; where growth stimulation and enhanced feed conversion is desirable in the animal, one may use from about 0.001 to about 0.03 g. (preferably from about 0.01 to about 0.02 g.) of methyl 18-O-(tetrahydro-2-pyranyl)-reserpate per 1000 g. of feed.

Example 44

To 2.0 g. of methyl 10-bromo-reserpate in 22 ml. of N,N-dimethylformamide and 2.0 ml. of 2,3-dihydropyran is slowly added 1.2 g. of p-toluenesulfonic acid in 7 ml. of N,N-dimethylformamide. During the addition, the reaction mixture is stirred and agitation is continued for an additional thirty minutes. The reaction mixture is diluted with ethyl acetate, the organic layer is washed twice with 25 ml. of an aqueous solution of sodium carbonate and once with water. The solvent is evaporated, the oily residue is washed well with water to remove remaining N,N-dimethylformamide and is then dissolved in ethyl acetate. The solution is dried over sodium sulfate and the solvent is removed to leave the light yellow methyl 10-bromo-18-O-(tetrahydro-2-pyranyl)-reserpate, M.P. 131-139°.

The starting material used in the above reaction may be prepared as follows: A solution of 2.62 g. of bromine in 92 ml. of acetic acid is added dropwise to 10 g. of

reserpine in 200 ml. of acetic acid while stirring. The reaction mixture is stirred for an additional ten minutes, the precipitate, representing the 10-bromo-reserpine hydrobromide, is filtered off and washed with acetic acid and ether. The free base is obtained by distributing the salt between chloroform and a 5 percent aqueous solution of sodium bicarbonate. The organic layer is removed, washed with water, dried over sodium sulfate and evaporated. The 10-bromo-reserpine crystallizes from methanol, M.P. 275-277°; yield: 4.70 g.

A solution of 13.4 g. of 10-bromo-reserpine in a 400 ml. of methanol, containing 1.2 g. of sodium, is refluxed for 1½ hours. The reaction mixture is concentrated to about 100 ml., diluted with 300 ml. of water, acidified to pH=1-2 with a 1:1-mixture of concentrated aqueous hydrochloric acid and water and extracted with methylene chloride. The aqueous phase is adjusted to pH=9-10 with aqueous ammonia, and the organic material is extracted with methylene chloride. The organic phase is dried over sodium sulfate, the solvent is removed under reduced pressure, and the residue is crystallized from ethyl acetate. The resulting methyl 10-bromo-reserpate is recrystallized from a mixture of ethyl acetate and methylene chloride, M.P. 229-230°; yield: 4.42 g.

Example 45

A total of 1.0 g. of 18-O-[2-(1,4-dioxanyl)]-reserpic acid is added in small amounts to an ether solution of diazoethane. After the gas evolution has ceased, the reaction mixture is allowed to stand at room temperature, and the excess diazo compound is destroyed by adding an ether solution of acetic acid. The solvent is evaporated, the residue is treated with dilute aqueous ammonia, and the organic material is extracted with methylene chloride. The organic phase is separated, dried and concentrated; the desired ethyl 18-O-[2-(1,4-dioxanyl)]-reserpate is isolated from the residue.

The starting material used in the above reaction may be prepared, for example, by refluxing 1.5 g. of methyl 18-O-[2-(1,4-dioxanyl)]-reserpate in 30 ml. of 1 N aqueous sodium hydroxide for three hours. The desired 18-O-[2-(1,4-dioxanyl)]-reserpic acid can be isolated according to the procedure described in Example 29.

In general, the compounds of the formula:

in which R₂, R₃', R₄, R₅ and R₆ have the previously given meaning, salts or N-oxides thereof, may be prepared by treating a deserpicidic acid compound of the formula:

in which R₂, R₄, R₅ and R₆ have the previously given meaning, or an N-oxide thereof, with a reactive ester of a hydroxy-cyclo-dioxa-alkane or a hydroxy-cyclo-oxathia-alkane, which contains at least five atoms as ring members, and in which the hydroxyl group is attached to one of the carbon atoms adjacent to a ring oxygen atom, in the presence of a condensing reagent, or by

replacing in deserpitate compounds having the formula:

in which R_2 , R_3' , R_4 , R_5 and R_6 have the previously given meaning, and R_1' represents lower alkyl, lower alkoxy-lower alkyl, tertiary amino-lower alkyl or the group of the formula $Ph-(Z)CH-$, in which Ph and Z have the previously given meaning, the esterified carboxyl group in 16-position by a free carboxyl group, and, if desired, separating a resulting mixture of isomeric compounds into the single isomers, and/or, if desired, converting a resulting salt into a free compound, and/or, if desired, converting a resulting compound into a salt or an N-oxide thereof.

These reactions may be carried out as according to procedures previously described for the preparation of analogous compounds. Halogeno-cyclo-dioxa-alkanes or halogeno-cyclo-oxathia-alkanes, in which the halogen atom is attached to one of the carbon atoms adjacent to the ring oxygen atom, such as 2-chloro-1,4-dioxane or 2-chloro-1,4-oxathiane, are the preferred reactants; N,N -dimethyl-formamide represents a very suitable condensing reagent, which may simultaneously serve as a solvent. The esterified carboxyl group of the formula $R_1'-O-(O=)C-$, in which R_1' has the previously given meaning, may be converted into the free carboxyl group by hydrolysis or, if R_1' represents the radial $Ph-(Z)CH-$, by hydrogenolysis.

The compounds obtained according to the methods of this invention may be converted into other compounds, for example, by introducing additional substituents. Thus, upon treatment with bromine, for example, according to the procedure described in Example 44, a bromine atom may be introduced.

What is claimed is:

1. A member of the group consisting of a compound of the formula:

in which R_1 represents a member of the group consisting of lower alkyl, lower alkoxy-lower alkyl, in which lower alkyl separates lower alkoxy from the carboxy group by from two to three carbon atoms, and N,N -di-lower alkyl-amino-lower alkyl, in which lower alkyl separates N,N -di-lower alkyl-amino from the carboxy group by from two to three carbon atoms, R_2 represents lower alkyl, R_3 stands for a member of the group consisting of 2-cyclo-oxa-alkyl having from five to seven atoms as ring members, lower alkyl-substituted 2-cyclo-oxa-alkyl having from five to seven atoms as ring members, and halogeno-substituted 2-cyclo-oxa-alkyl having from five to seven atoms as ring members, each of the groups R_4 and R_5 represents a member of the group consisting of hydrogen, lower alkyl, lower alkoxy, lower alkyl-mercapto and halogeno, and R_6 , attached to one of the positions 5 and 6, stands for a member of the group consisting of hydrogen and lower alkyl, an N-oxide thereof and a therapeutically acceptable mineral acid addition salt of said compound.

2. The compound of the formula:

in which R_1 represents lower alkyl having from one to four carbon atoms.

3. Methyl 18-O-(tetrahydro-2-pyranyl)-reserpate.

4. Methyl 18-O-(tetrahydro-2-pyranyl)-reserpate N-oxide.

5. Ethyl 18-O-(tetrahydro-2-pyranyl)-reserpate.

6. n-Propyl 18-O-(tetrahydro-2-pyranyl)-reserpate.

7. Methyl 18-O-(tetrahydro-2-furanyl)-reserpate.

8. The compound of the formula:

in which R_1 represents lower alkyl having from one to four carbon atoms.

9. Methyl 18-O-(tetrahydro-2-pyranyl)-deserpitate.

10. 18-O-(tetrahydro-2-pyranyl)-reserpic acid.

11. A member of the group consisting of a compound of the formula:

in which R_1 represents a member of the group consisting of lower alkyl, lower alkoxy-lower alkyl, in which lower alkyl separates lower alkoxy from the carboxy group by from two to three carbon atoms, and N,N -di-lower alkyl-amino-lower alkyl, in which lower alkyl separates N,N -di-lower alkyl-amino from the carboxy group by from two to three carbon atoms, R_2 represents lower alkyl, R_3 stands for a member of the group consisting of 2-cyclo-1,4-dioxahehexyl, lower alkyl-substituted 2-cyclo-dioxahehexyl, halogeno-substituted 2-cyclo-1,4-dioxahehexyl, 2-cyclo-1,4-oxathiahehexyl, lower alkyl-substituted 2-cyclo-1,4-oxathiahehexyl, and halogeno-substituted 2-cyclo-1,4-oxathiahehexyl each of the groups R_4 and R_5 represents a member of the group consisting of hydrogen, lower alkyl, lower alkoxy, lower alkyl-mercapto and halogeno, and R_6 , attached to one of the positions 5 and 6, stands for a member of the group consisting of hydrogen and lower alkyl, an N-oxide thereof and a therapeutically acceptable mineral acid addition salt of said compound.

12. Lower alkyl 18-O-[2-(1,4-dioxanyl)]-reserpate.

13. Methyl 18-O-[2-(1,4-dioxanyl)]-reserpate.

14. Lower alkyl 18-O-[2-(1,4-oxathianyl)]-reserpate.

15. Methyl 18-O-[2-(1,4-oxathianyl)]-reserpate.
